UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

ASSEMBLING MACHINE.

Application filed June 15, 1921. Serial No. 477,709.

My invention relates to machines for bringing together various articles to form a composite object, and is illustrated as embodied in a machine designed for assembling the parts of the sole of a shoe. By a machine of this character, a shoe-bottom, including, for example, a sole, an element for stiffening the shank-portion of such sole and an element for occupying the space over the insole of a shoe between the inner edges of the welt, may be united to furnish a unit ready for attachment to a lasted upper by a single bottoming operation. Such a unit is described and claimed in Letters Patent of the United States No. 1,582,259, issued April 27, 1926 on the application of Frederick M. Furber, now deceased.

An object of the invention is to provide an assembling machine which shall be to a high degree automatic in its action, holding upon a support, or a plurality of such supports furnishing a work-turret, one or more articles, to which other articles and the means for maintaining their association are supplied, preferably at successive operating positions. Thus, a primary element, as a sole, may be delivered from a container or other holding means to a support and there secured, and thereafter portions of the supported sole may receive such a retaining means for auxiliary elements as a coating of an adhesive, and these elements, as a shank-piece, preferably heated, and a filler-piece applied over the coated surface, which has been maintained plastic, and the associated articles pressed into intimate contact. Finally, the composite object formed by these operations is released from its support and removed.

For such operations upon the work as have just been outlined, it should, whatever its size, be correctly located with respect to the mechanisms which are to perform said operations, and should be securely held while being acted upon and released at the proper time. Moreover, it may be important that the performance of any assembling operation in a series shall be dependent upon the completion of an operation which normally precedes it. That is, if a composite sole is being assembled, the sole itself should be in po-

sition before the auxiliary elements or their retaining means are supplied. All these results are attained in the present invention by my work-support and its co-operating elements.

In the attainment of a further object of the invention, I furnish effective means for transferring the articles from their containers to places at which they are held, such means so maintaining the articles during their travel that they will not accidentally be disengaged, and, with the turret arrangement of multiple supports and plural operating positions, requiring little space in which to move, and avoiding interference with one another.

It is desired that the articles transferred, and particularly the soles, shall occupy upon their supports predetermined positions, and this condition I satisfy by adjusting them at their holding means prior to their transfer. This adjustment may be accomplished partially while within a container, in part during their initial feeding from such container, and in part after delivery from the container and while they are awaiting transfer, and is preferably in a plurality of directions, as transversely and longitudinally of a sole. Since the articles, as is the case with molded soles, may be not only curved, but lacking uniformity in their shape, and as I choose to feed these through a relatively narrow opening, my invention involves means for accomplishing this feed with certainty, irrespective of the curvature.

An additional object of the invention concerns the provision of a container for a considerable number of articles to be delivered, as the shank-pieces, and their effective presentation to the device which is to transfer them. I have also included easily operated means whereby, when the container has been emptied, it can be restored to its initial position for the reception of an additional supply, together with an arrangement for quickly introducing such supply into the container.

To produce a better union of the assembled articles, one of them, the shank-piece for example, may be heated, and an object of the invention is to apply this heat in an efficient manner.

It may be desired to differently apply certain of the articles, and this object the present invention accomplishes, there being means illustrated for varying the position in which the shank-pieces are deposited and, correspondingly, the securing adhesive.

Still another object of my invention is to present to the work-support, in the correct relation and without the introduction of complicated instrumentalities, one of the articles, which in the composite sole may be the filler-piece. When pressure is to be applied to this article to force the assembly together, great simplicity and precision are attained by utilizing the pressure member as a portion of the delivering or transferring means.

An additional object of the invention is to provide a portable magazine or container, into which such articles as filler-pieces may be loaded and applied, as desired, to the machine in which they are to be used, this magazine holding the contents against displacement during filling and application to the machine, and having simple co-operating means to release the articles when this application is being effected.

The machine should not, of course, start in operation until its various portions are in condition to functionate properly. Such premature action it is a still further object of my invention to guard against, and I have so arranged that when heat is employed, as to prepare the adhesive or the shank-pieces for application, power will not be communicated to the various operating mechanisms until there is a sufficient elevation of temperature. I also, in connection with an actuating force furnished by fluid pressure, prevent its application until it has reached a predetermined operative magnitude.

Other objects of the invention will herein after be developed.

One of the many embodiments which my improved machine may assume is illustrated in the accompanying drawings, in which

Figs. 1 and 2 are top plan views, which, when taken together, show in a diagrammatic manner the entire apparatus;

Fig. 3 is a horizontal section, illustrating particularly the gearing for driving the turret and operating mechanisms at the various positions;

Fig. 4 is a side elevation of a portion of the driving mechanism for the first, second and third operating positions, parts being in section;

Fig. 5 is a top plan view of the same mechanism, here also portions being sectioned;

Fig. 6 is a vertical, sectional detail on the line 6—6 of Fig. 5;

Fig. 7 is a like view on the line 7—7 of Fig. 5;

Fig. 8 (Sheet 4) is a sectional detail through the valves of the air-pump;

Fig. 9 is a top plan view, partially in sec-

tion, of the driving mechanism at the fourth operating position, acting upon said position and also upon the succeeding position;

Fig. 10 is a vertical sectional detail through clutch mechanism included in the driving mechanisms at the operating positions;

Fig. 11 is a transverse section on the line 11—11 of Fig. 9;

Fig. 12 illustrates, in side elevation, a portion of the turret and one of the work-supports, with parts broken away;

Fig. 13 shows, in side elevation, the mechanism at the first operating position, together with a work-support in co-operation therewith;

Fig. 14 is an enlarged, broken side elevation of the sole-container, transferring mechanism and actuating mechanism therefor at the first operating position;

Fig. 15 illustrates the same elements in end elevation;

Fig. 16 is a transverse, sectional detail on the line 16—16 of Fig. 15;

Fig. 17 is a top plan view of the sole-container and more closely associated parts;

Figs. 18 to 21, inclusive, represent, in vertical, sectional detail, successive positions of the sole-presenting mechanism;

Fig. 22 is a broken side elevation of the cementing mechanism at the second position;

Fig. 23 is a top plan view illustrating said mechanism;

Fig. 24 is a side elevation, with parts in section, of the cement-applying nozzle;

Fig. 25 is a horizontal section on the line 25—25 of Fig. 24;

Fig. 26 illustrates a modification of the device for actuating the cement and air-controlling valves;

Fig. 27 is a transverse section on the line 27—27 of Fig. 28;

Fig. 28 is a detail in top plan of the driving mechanism for the cement-applying mechanism and the turret;

Fig. 29 is a horizontal, sectional detail through this driving mechanism on the line 29—29 of Fig. 22;

Fig. 30 shows, as a side elevation, the shank-supplying mechanism at the third operating position;

Fig. 31 is an enlarged vertical, sectional detail through the elevating mechanism for the shank-piece-container;

Fig. 32 is a horizontal section on the line 32—32 of Fig. 31;

Fig. 33 is an enlarged side elevation of a portion of the threaded container-elevating rod, with a section broken away;

Fig. 34 shows in end elevation a portion of the gearing for intermittently rotating the shank-piece-container;

Fig. 35 is a partial, enlarged, central vertical section through the shank-piece-container and immediately adjacent actuating mechanism;

Fig. 36 shows in side elevation, with parts broken away, a portion of the actuating mechanism for the transfer device associated with the third operating position;

5 Fig. 37 is a horizontal section on the line 37-37 of Fig. 36;

Fig. 38 is a vertical section of a portion of the driving connections for the transferring device;

10 Fig. 39 illustrates, in broken side elevation, the filler-applying and work-pressing mechanisms at the fourth operating position;

Fig. 40 shows, partly in end elevation and partly in vertical section, the feeding mechanism for the filler pieces;

15 Fig. 41 is a horizontal, sectional detail on the line 41-41 of Fig. 39;

Fig. 42 (Sheet 17) is a broken top plan view of the filler-container;

20 Fig. 43 is a side elevation, partly in section, more particularly illustrating the driving mechanism at the fourth operating position;

Fig. 44 (Sheet 1) is an enlarged horizontal, sectional detail taken just above the air-controlling valve at the fourth position;

25 Fig. 45 shows, in side elevation, the work-removing mechanism at the fifth operating position, together with a magazine for receiving the work;

30 Fig. 46 is a detail in perspective of cam-surfaces at the fifth position for exercising control over elements of the work-support;

35 Fig. 47 is an enlarged transverse, vertical sectional detail through the container-advancing mechanism at the fifth operating position; and

Fig. 48 shows these same parts in side elevation, with portions broken away.

40 There will first be described the work-supporting turret with its driving mechanism, together with a general statement of the relation thereto of the co-operating mechanisms for acting upon the work, this being followed by detailed descriptions of each of said operating mechanisms taken in the order in which they act to produce a complete article, and there being a concluding outline of the operation of the entire machine.

50 *Turret, general arrangement of operating mechanisms and driving mechanism therefor (Figs. 1 to 12, inclusive, 22, 28 and 29).*

55 Rising from the center of a base 50 is a tubular standard 52, here illustrated as made up of a plurality of sections, one upon the other, and having arranged to turn about the lower section a sleeve 54, which is stepped at its lower extremity upon a suitable anti-friction bearing 56. Radiating symmetrically from the sleeve with respect to their angular arrangement in a horizontal plane are arms 58 bolted to the sleeve, there being five of these arms shown. Carried upon the upper surface of each arm is a work-support, furnished by a skeleton block 60. These

work-supports upon each of the arms are identical as to their construction and directly associated elements, so that but one of these need be described in detail. The upper and lower faces of the support 60 correspond in

70

contour to the objects to be operated upon, in the present instance these consisting of soles for shoes, of which one is illustrated at S; see particularly Fig. 12 of the drawings. When used in connection with shoe soles, 75 since these are in pairs differently formed for the right and left shoes, the opposite sides of the support are correspondingly shaped, said form being attached to its arm at 62 for ready reversal.

80

To fix the sole in predetermined position longitudinally of the support, some such locating device as a pin 64 is caused to project through the support, being carried upon the arm 58 and arranged to move in a longitudinal slot in the support. This pin may enter an opening o, situated near the center and close to the rear edge of the sole. In the present instance, I have shown the soles operated upon as of such length that each will terminate upon the shoe in proximity to the breast of the associated heel, these being known as "short soles". Since it is desired that at the opposite end of the support the toe portion of the sole shall always lie at the same point, the pin 64 is adjustable longitudinally of the arm, it rising vertically from

85

a slide 66 movable in ways thereon, and being urged normally outward by a spring 68 located in a recess in the arm and bearing against the inner end of the slide. The movement of the pin with its slide to the correct position to receive the particular length of sole to be operated upon is effected by actuating means at the last operating position

90

of the support, this contacting with a roll 70 rotatably mounted in a horizontal plane at the outer extremity of the slide. The adjustment of the pin 64 through the action of the controlling means upon this roll will hereinafter be described in detail. When ad-

100

justed, the slide and pin are temporarily locked by a lever 72, pivoted upon the arm and having a wedge-shaped cam-portion 74 entering a groove in the under portion of the slide. A spring 76 so swings the lever upon its fulcrum that the cam-portion normally acts to hold the slide against outward move-

110

ment by the spring 68. It is released by upward pressure upon a roll 78, rotatable upon an outwardly extending arm of the lever and governed by a contact device, the action of which will be discussed in connection with that acting upon the roll 70.

115

When a sole rests upon the upper surface of the support with its heel end in engagement with the pin, and its toe end adjacent to the inner extremity of the support, it is engaged by a retaining device, which holds it for the various operations which are to be performed.

120

125

130

The like devices cooperating with the supports each includes a substantially vertical lever 80 fulcrumed upon the lower portion of the supporting arm 58 and having an end or carrier-portion 82, which may be held in different vertical positions by a binding-screw 84, thus adapting the device carried by it for effective co-operation with soles of different thickness. Arranged to slide horizontally in the lever-portion 82 is a contact member 86, having at its outer end an inclined face 88, which may generally conform to the vertical edge of the sole to be engaged. A spring 90, interposed between the lever-portion 82 and the slide 86, urges the latter toward the support, movement in this direction being limited by nuts 92 carried upon the threaded inner end of the slide. The sole engaging slide is recessed to receive one arm of a bell-crank lever 94 fulcrumed upon an overhanging arm of the lever-portion 82, and having projecting downwardly, outside the inclined face 88, a sharpened or serrated edge 96, adapted to grip the upper surface of a sole upon the support. To bring about the normal engagement of this retaining device with the sole, a spring 98 connects the lever 80 and the lower portion of the arm 58. The retaining device may be latched out of engagement with the sole by a lever 100 fulcrumed upon lugs depending from the arm beneath the support, and recessed at its end at 102 to receive a stud 104 projecting horizontally from the side of the lever 80. The opposite or outer end of the latching lever 100 is engaged by a contact-head 106, carried upon a vertically movable member or pin 108 mounted to slide in the arm and extending through an opening near the center of the support, this preferably being at the lowest point of the curved tread-portion of the sole. The length of the pin is such that it may, when there is no sole upon the support, be projected above the surface of the latter, it tending to remain at the position to which it is elevated under the influence of a lightly acting friction device 110 carried by the arm 58. When the pin 108 is held down by the contact of a sole located upon the support, as is illustrated in Fig. 12, the latching depression 102 of the lever 100 is maintained above the plane of the co-operating stud 104, so that the spring 98 may exert its tension to draw the retaining device into engagement with the sole. As the contact of the face 88 with the edge of the sole forces the member 86 to the left (Fig. 12), the bell-crank lever 94 is turned in a clockwise direction to force its gripping portion 96 into the upper surface of the sole. At the same time, the head 106 of the pin acts upon a bell-crank lever 112, fulcrumed beneath the arm 58 and having upon one arm a fork engaging a stud extending across the head, and at the other a similar fork acting upon a slide 114 mounted to move horizontally in the arm. The outer end of the slide 114 has rotatable upon it a roll 116, which exercises a controlling function at various operating positions. In the first position, on account of the absence of a sole when the support 60 arrives at this point, the pin 108 is elevated, and the roll 116, controlled by its connection thereto, lies in a vertical plane differing from that which it occupies at the other four operating positions, at which a sole is upon the support and is depressing the pin. On account of this relation, the bringing into action of the operating mechanisms at the positions between the second and the fifth may be prevented, unless a sole has been properly applied to the support at the first position. This will be made clearer as the description progresses. The lever 80 may be released from its latch 100 by the contact of a roll 118 on its upper extremity with a fixed element, which will be described in connection with the fifth operating position. The spindle of this roll is vertically adjustable, being held in place by a binding-screw 120, this allowing the variation in the height of the lever-portion 82 to be compensated for, so that a fixed relation between the roll and its actuating element is maintained.

It will be seen that the rotatable sleeve 54 with its radial arms 58 and the supports 60 carried thereby form a turret upon which a plurality of pieces of work may be subjected simultaneously to different operations, and said turret revolved step by step to bring the supports to the positions previously occupied by companion supports, to be there subjected to other operations, until a complete cycle of the machine has been effected. To permit these various operations to be performed, there are arranged about the turret, they being separated by angles corresponding to those between the arms 58, five mechanisms, occupying positions designated as A, B, C, D and E, these being most clearly illustrated as to their relation in Figs. 1 and 2 of the drawings. In the present machine, at position A, the soles S, preferably molded to a form adapting them for application to the bottom of a lasted shoe, are transferred one by one from a container or magazine, and applied to successive supports 60. Having been fixed upon the support, as hereinbefore indicated, the sole is conveyed by its support to position B, at which a portion of its upper surface receives a coating of an adhesive fluid. Then, upon transfer to position C, the adhesive condition of the fluid is maintained, and a heated stiffener or shank-piece is lifted from a container or magazine and laid upon the coated area. Further movement to position D taking place, a filler-piece of sheet material, designed to occupy the space over the forepart of the insole of a lasted shoe between the drawn-over edges of the upper, is taken from a container, placed over the shank-piece, and the adjacent surfaces of the

three assembled elements pressed firmly together to join them. Finally, at position E, the thus completed composite sole is removed from its support and deposited in a receiver-magazine, ready for utilization elsewhere.

To impart the desired intermittent rotation to the turret, and to furnish power for the mechanisms at the operating positions, the driving mechanisms, best illustrated in Figs. 10 to 15, inclusive, 22, 28 and 29, may be employed. Mounted upon the base is shown a motor 130. This, through an extension of its shaft 132, rotates a worm 134 meshing with a worm-wheel 136 carried upon the periphery of a casing 138 turning about a shaft 140 journaled in a vertical position in the base. The casing carries, rotatable within it, pinions 142, 144 of a planetary system, they respectively engaging a fixed pinion 146 carried upon a sleeve 147 surrounding the shaft 140, and a pinion 148 fast upon the spindle 140. This last-mentioned pinion contains one more tooth than the fixed pinion, resulting in the transmission, through the planetary system from the worm-gearing, of a much reduced rate of rotation to the shaft 140. Secured upon the shaft 140 is a driving element 150 of a Geneva stop movement; see particularly Fig. 29 (Sheet 15), the driven element 152 of the stop movement being fast upon a shaft 154 rotatable in the base parallel to shaft 140. Fixed to the shaft 154 is a gear 156 meshing with a gear 158 upon the sleeve 54 to cause the rotation of the turret. The effect of this whole chain of gearing is to transmit motion from the motor-shaft 132 to the turret at an extremely low speed ratio. Upon the shaft 140 is secured a gear 155 engaging a pinion 157 loose upon the shaft 154. From this pinion 157, power is delivered to the operating mechanism at position B, as will be later explained. The effect of the elements 150 and 152 of the Geneva stop mechanism is to impart to the turret, through the gearing 156 and 158, rotation, with intermediate periods of rest. As the mechanism is illustrated, this produces movement of the turret for an interval one-half that during which it rests. This enables the operating mechanisms associated with the turret to act at each of the positions for a predetermined time, and then for the turret to be rotated during a less time to bring the supports to the succeeding positions. The Geneva movement is of peculiar utility in the present connection, because it permits a gradual starting and stopping of the movement without subjecting the elements to strain. In addition to driving the turret and the operating mechanism at position B from the shaft 140, power is transmitted to positions A and C from said shaft through sprocket-gearing 160 and 162, respectively (Fig. 3). As illustrated, a separate motor 164 actuates the mechanisms of positions D and E (Figs. 9 and 43). The

shaft 166 of this motor is connected by worm reducing-gearing 168 to an intermediate shaft 170, the speed being further reduced through worm-gearing 172 for the mechanism of position D. From this position sprocket-gearing 174 communicates motion to the mechanism of position E.

It is preferable to delay the application of power to the machine until the required amount of heat has been applied, as at positions B and C, to the adhesive and shank-pieces to place these elements of the composite sole in condition for satisfactory assembling. I have provided means for automatically controlling this effect, acting upon an extension of the motor-shaft 132. Between independently rotatable sections of this is included a clutch 176 (Figs. 4 and 5), which may be of the friction type, the driving element being rotated by the motor 130, and the driven element turning the worm 134 when the clutch elements are in engagement. The driven element is splined for longitudinal movement in the usual manner upon the outer section of the extension of shaft 132, and is acted upon by a wedge 177 carried upon the lower extremity of a rod depending from a piston 175 operating within a cylinder 178. A spring 179, surrounding the piston-rod, exerts its expansive force to hold the piston normally toward the upper head of the cylinder and the wedge out of active engagement with the clutch element, which is separated from its companion by the usual spring. To the cylinder 178 air under suitable pressure is supplied from a tank 180 through a pipe 181. Pressure may be created in this pneumatic system by a continuously operating pump 182, acting through a crank-shaft 183 driven by spiral-gearing 184 from the motor-shaft 132. The pump may be of any construction adapting it for the work, a suitable arrangement of valves being as illustrated at 173 in Fig. 8 of the drawings. The magnitude of the pressure in the system is governed by a device included in the pipe 181 and comprising a casing 185 (Fig. 7) having in its lower portion a passage 186, communicating through ports to two chambers containing, respectively, valves 187 and 188. The valve 187 is of such weight that the pressure of air in the supply-pipe will not open the port controlled by this valve into the passage 186 until such pressure has risen to an amount which will effectively act in the system. That is, air is not supplied to the cylinder 178 until it exerts force enough to properly operate the clutch 176, the same being true of the other mechanism to which pneumatic pressure is applied. The valve 188 is of such weight that it will be lifted from its seat when the continuously acting pump has created an excessive pressure, at this time, the system being relieved by escape of the air through the port gov-

erned by this valve and through a discharge-passage 189 in the casing 185. The presence or absence of effective pressure in the system is controlled by a valve 190 co-operating with an opening through the side of a casing 191 communicating with the pipe 181 between the pump 182 and the tank 180. The valve 190 is carried by a thermostatic device 192, which may be provided by any appropriate heat-responsive device, it being shown as of the multiple disk type. This thermostat is under the influence of the means for applying heat to the operating mechanisms. In the present embodiment of the invention, this heat is generated by electric current flowing through resistance units. Included in this circuit, preferably in parallel, by conductors 193, is a unit 194 mounted upon the side of the casing 191, so that the heat which it develops is communicated to the thermostat 192. The heat applied by this unit bears such a relation to the heat utilized at the operating positions that when it is of the correct degree at the latter, that at the thermostat will be sufficient to cause it to operate and close the valve 190. Up to this time, the air in the pneumatic system will have been permitted to exhaust through the opening in the casing 191, so there will have been insufficient force exerted to raise the valve 187 and start the controlled operating mechanisms through the engagement of the clutch 176.

Operating position A—sole-supplying mechanism (Figs. 13 to 21, inclusive).

Rising from the base of the machine is a standard 200 located in alignment with one of the positions at which the work-supports are stopped by the driving mechanism, and having at its upper extremity a container for the soles S. This container includes a table 201 extending horizontally at the top of the support and including a laterally projecting portion over which the soles are fed and upon which they await transfer to a support 60. Projecting vertically above the tables are an end container-wall 202 and opposite side walls 204 and 206. The side walls are shown as supported upon the end wall by frames 208 mounted upon rods 210, 210 movable in guides 212 fixed upon the end wall. Upon each of these rods is a projection 214 entering a cam-groove in a disk 216 rotatably supported upon the wall 202. A hand-wheel 218 permits the cam-disk to be turned, and by the engagement of its groove with the rod-projections, move the side walls toward and from each other in a predetermined relation. This may not be at an equal rate, since the relative lengths of the heel and forepart portions of a sole may vary for different sizes, and the cam-groove is designed to accomplish the relative movements of the sides to maintain the longitudinal centers of the varying sizes of soles at a constant point. To facilitate the

setting of the walls, an indicating finger 220 is fixed upon the end wall and overhangs the edge of the disk 216, upon which disk may be placed an indicating scale, the divisions of which correspond to sole-lengths. The delivery side of the container may be closed against movement of all save the lowest sole in this direction, by a vertical bar 222 movable in ways at the end of a bracket 224 projecting upwardly from the edge of the table. The lower end of this bar may be differently spaced from the surface of the table by means of a screw 226 threaded into a lug upon the end of the bracket 224 and arranged to turn in a projection from the bar. The adjustment of this bar provides for the proper passage beneath it from the container of soles of different thickness. The bracket 224 is arranged to move upon the table to alter the relation of the bar 222 to the wall 202, this adjustment being effected by a slot-and-screw connection 228. This movement of the bar differently disposes it to best co-operate with soles of different widths. The lower convex surfaces of the molded soles rest upon the table 201, while their upwardly curved shank-portions are supported above this level by a shelf 230 projecting beneath the wall 204. The height of this shelf may be changed by a screw-and-slot connection 232, by which it is attached to the side of the standard 200. In this way, soles of different curvatures may be correctly leveled in the container for engagement by a feeding device.

Formed in the top of the table, substantially at right angles to the longitudinal axis of the support 60, is a slot 234, along which, in ways, is mounted to move a slide 236. This slide has depending portions 238, upon which are pivoted blocks 240 engaged by the forked ends of a lever 242 fulcrumed upon the standard 200. A roll 243 upon the lower extremity of the lever enters a cam-track 244 in a disk 246. This cam-disk is secured upon one extremity of a shaft 248 journaled horizontally upon the base 50 and standard 200 and being in sections, its portions being connected to rotate together by a clutch 250. The clutch may be a single-rotation device of any convenient form, in the illustrated machine the clutches at positions A, C, D and E being substantially identical, differing merely in the manner in which the driving element is rotated. One of these, that of position D, is illustrated in detail in Figs. 10 and 11 of the drawings. It is only necessary to say that this is of the jaw type, having engaging projections 252, which are normally separated by a spring 254. The driven element of the clutch has an inclined surface for engagement by an actuating wedge 256 and a track 258 to receive a roll 260 movable with the wedge. When the wedge 256 is forced down to bring the clutch elements into driving engagement, the roll 260 is caused to roll along the track 258, driving the clutch element and the cam-disk 246.

- ing engagement against the expansive force of the spring, the roll 260 moves from a radial portion to a circular portion of the track 258, this latter portion holding the wedge 256 in engagement with the inclined surface of the driven element until, after this has turned through substantially 360 degrees, the roll is again forced out into the radial portion, permitting the spring to release the clutch.
- 5 The wedge 256 is carried by a vertical rod 262 arranged to slide in brackets 264 upon a standard 265 secured to the base adjacent to the standard 200. A spring 266 surrounds this rod, pressing it normally upward to move the wedge away from the driven element of the clutch and to carry the roll 260 into the radial portion of the cam-groove 258. The upper extremity of the rod 262 carries an inclined contact-surface 268, which lies beneath 10 the path of the roll 116 of the support 60 when the supporting pin 108 is raised; that is, when there is no sole in place upon the support. Rotation is imparted to the shaft 248 to oscillate the lever 242 and reciprocate the slide 236, by bevel-gearing 270 from a vertical shaft 272 by the sprocket-gearing 162 operated by the shaft 140.
- 15 The primary slide 236 carries in its reciprocation, movable in horizontal ways in it, a secondary slide 274, provided with a portion 276 extending rearwardly with respect to the direction of sole delivery. Upon lugs depending from the slide 274 is fulcrumed a lever 278, having at its inner end rolls 280 lying 20 between bifurcations of the portions 238. A spring 282, situated between the bottom of the slide and an arm of the lever 278, holds the rolls normally in a raised position in contact with the upper walls of the bifurcations.
- 25 At the forward side of the slide 236, conveniently movable in the same ways, is a slide 284, which is forced toward the slide 236 by a spring 286 surrounding a rod 288 supported at its extremity upon the table 201. Pivoted 30 beneath the slide 284 is a lever 290, acted upon by a spring 292 interposed between its arm and the slide 284 to hold its forked end 294 in horizontal alinement with the lever 278. The slide 274 has a notched inner edge 296, 35 formed as best shown in Figs. 18 to 21 of the drawings, there being a downwardly inclined surface upon which the edge of the lowest sole may rest, and a shorter upwardly inclined surface for contact with the vertical sole-wall. In the normal position of the slide 274, the juncture of these walls lies in substantial alinement with the container-wall 202, and the front bar 222 is so adjusted that as the soles descend in the container, their 40 angular edge practically coincides with the angle of the notch. Since the portion 276 of the slide is above the surface of the member 236 upon which the body of the lowest sole rests, the outer edge is elevated by the slide 274, so that the sole as a whole is inclined for- 45
- wardly and downwardly, it contacting near the maximum width of the forepart with the forward portion of the slide 236 only over an area immediately adjacent to its edge. This provides for the ready passage of the lowest sole beneath the lower extremity of the bar 222, regardless of whether it is a right or a left, and whatever its curvature. As the lever 242 swings toward the left, as viewed in Fig. 18 of the drawings, under the influence of its actuating mechanism, the slide 236 moves through the slot 234 toward the lateral extension of the table, carrying the lowest sole upon it. By the connection of its lever 278 with the bifurcation of the portions 238 of the slide, the slide 274 also advances at the same rate, its notched portion pushing upon the outer edge of the sole. The combined action of the two slides carries the lowest sole partially beneath the bar 222 on to the table at 50 the side of the container. When the sole has assumed the position shown in Fig. 19, the formation of the cam-track 244 causes the slide 274 to be withdrawn, as appears in Fig. 20, this being sufficient to carry the notched edge away from the sole, which thereupon assumes a substantially horizontal position upon the slide 236. This retreat of the auxiliary slide is not sufficient to permit the succeeding sole to fall into the notch, it remaining upon the upper face of the slide. After the dropping of the lowest sole, the cam-track causes the auxiliary slide to again move forward, pressing with its extreme edge against the adjacent edge of the sole. This carries said sole completely out of the container beneath the wall 222, the remainder of the stack then resting upon the extension 276. As this last movement progresses, one of the rolls 280 comes into contact with the fork 294 of the lever 290, causing the slide 284 to travel from the container, and compressing the spring 286. The levers 278 and 290 now act as a toggle having equal arms, and their connections, furnished by the roll and fork, are caused by the pressure to descend in the bifurcation. A vertical plane through the center of the bifurcation coincides with the axis of the support 60, upon which the sole is to be laid. Therefore, the movement of the levers 278, 290 causes the adjacent edges of the slides 274 and 284 to be symmetrically disposed upon the opposite sides of the slide 236, and the sole to be centralized laterally thereon, locating it in the proper position to be transferred to the support. The cam-track 244 now allows all three slides to rest in the position just described, for the transfer of the positioned sole.
- 55 By the mechanism just described, a sole has been placed upon the extension of the table 201 in generally correct relation as to its transverse position. There remains its adjustment longitudinally, and a final correction of its transverse relation. To accom- 60

plish these operations, I have provided opposite side contact members 298, 298 and a toe contact member 300 projecting above the table the members 298 being arranged to move 5 through openings in the shelf 230. Said members 298 are preferably in the form of fingers pivoted upon levers 302, 302 fulcrumed at the upper ends of the arms of a yoke 304, which is fixed at the top of a vertical sleeve 306. This sleeve has a bearing for longitudinal movement in a bracket 308, its movement being resisted to the desired extent by an adjustable friction device 310, the purpose of which will appear shortly.

10 Through the sleeve 306 passes a rod 312, the lower end of which carries a stud projecting into a slot in an arm 314 pivoted upon the standard 200. Upon the end of the arm is a roll 315, entering a cam-track 316 in the disk 246.

15 Near the upper extremity of the rod 312, at its opposite sides, are formed racks 318, 318, which mesh respectively with gear-segments 320, 320 upon the levers 302, 302. The fingers 298, 298 are shown as drawn normally 20 toward each other, and also toward the table by a helical spring 322, joined at its extremities to the fingers, and resting at its side with some force against an upward extension 324 of the rod. This deflects the spring to one side of a straight line between the fingers, as is best shown in Fig. 14 of the drawings, tending to always draw them to the left, as viewed in this figure, as well as to move them toward one another. The toe member 300 is furnished by an upwardly extending arm of a bell-crank lever, the generally horizontally extending arm 328 of which is held normally upward by a spring 326 connecting the lever with the standard. The effect of this spring 25 is to hold the toe member away from the sole as it rests upon the table 201. The arm or contact portion 300 of the lever is yieldable from the companion arm, being drawn into contact with it at 330 by a spring 332 uniting the arms. This enables the member 300 to be moved against the toe portion of a sole and hold it while the actuating movement of the arm 328 continues. Pivoted upon its lower portion, the rod 312 carries a pawl 334 with 30 its engaging end drawn inwardly toward the standard by a spring 336. When the rod travels down, a horizontally extending arm of the pawl comes in contact with a cam-projection 338 carried upon the outer side of the standard, and serving to swing the engaging end of the pawl outwardly. In their normal position, the upper ends of the fingers 298 are below the rear portion of the sole which rests upon the shelf 230 with its cut-off portion adjacent to a gage-wall 340, against 35 which the straight edge of the sole is to be squared. This wall is shown as continuous, but should at least be arranged to engage the sole-edge at separated points. It is mounted 40 to move laterally across the shelf with the side wall 204 of the container, sliding over the shelf so that in the adjustment of the container-walls for soles of different lengths, the gage-wall bears a fixed relation to the container-wall. It is constrained to thus 45 move by projections 342 passing through sockets in the wall-supporting frame 208. These projections are capable of moving vertically through the sockets, so that as the shelf 230 is adjusted for soles of different 50 forms, the gage-wall may rise and fall with it. When the cam-track 316 in its travel begins to act upon the rod 312, its first effect is to move the racks 318, 318 upwardly past the gear-segments 320, the friction device 310 resisting the movement of the sleeve and yoke 55 which supports the fingers 298. The effect of this rack-and-gear connection is to separate the fingers, so that their adjacent edges may be farther apart than the maximum width of the sole to be operated upon. The separation having been accomplished, the lower teeth of the segments strike upon the plane surfaces of the rod 312 below the racks. This 60 compels the rod and yoke to move together, lifting the fingers until their upper ends are above the sole. The cam-track 316 then reverses the travel of the rod 312, and in its descent there is an opposite action, by which the racks, first acting upon the segments while 65 the sleeve and yoke are held stationary by the friction device, bring the fingers into engagement with the opposite edges of the sole, and then draw them down to true its longitudinal axis with respect to the axis of the support 60. 70 While the fingers are still acting, the pawl 334 engages the end of the lever 328, rocking this about its fulcrum to press the contact member 300 against the toe of the sole. This 75 forces said sole back against the gage-wall 340, the fingers yielding against the spring 322 by virtue of their pivotal connection to the levers 302 to permit this without interference. This action of the toe contact member 80 squares the straight rear edge of the sole against the gage-wall, thereby adjusting said sole angularly upon the supporting surface of the table. While the toe contact member 85 is maintaining its pressure, the fingers are drawn below the sole, and are restored to normal. As the end of the downward travel of the rod 312 is approached, the arm of the pawl 334 rides over the cam-projection 338, 90 swinging the pawl outwardly to release the lever arm 328. The spring 326 thereupon quickly moves the contact member 300 away from the toe of the sole, without any effect 95 tending to displace it laterally, leaving the sole positioned both longitudinally and transversely in the proper relation for transfer to the support 60. 100

105 A sole having thus been placed correctly upon the table 201 outside the container, it is transferred therefrom to the support which 110 is at that time aligned with the operating 115 120 125 130 135

mechanism of position A. A device 344, which directly engages the sole for this purpose, may be as illustrated in United States Letters Patent No. 1,438,481, issued December 12, 1922, on application of Frederick M. Furber. Here it will be sufficient to say that it includes spurs 346, 346, entering and being locked in engagement with the sole upon downward pressure against the latter, and 10 being released when a controlling lever 348 contacts with a projection 350 upon the central standard 52 of the turret. The transferring device is yieldably mounted upon the lower end of a vertical carrier bar 352, 15 its spindle 349 being pressed downwardly by a spring 351. This bar is pivotally supported upon arms 354, 354, carried by shafts 356, 356 journaled in an upward extension of the standard 265. Fixed upon these shafts are 20 gear-segments 358, 358, meshing with a rack-bar 360, guided in casings 362, 362 supported upon the standard, and in brackets 364 also fixed upon the standard. Pivoted near the lower extremity of the bar 360 is a block 366, 25 movable in ways at the end of a lever 368 fulcrumed upon the standard. This group of elements is best illustrated in Fig. 38, where the corresponding parts at position C appear. Articulated to the lever 368 is a connecting 30 rod 370, joined at its lower end to a crank 372, carried by the driven portion of the shaft 248. Initially, the device 344 occupies a position just above the table 201 at a point near the center of the sole placed thereon by 35 the feed mechanism of the container. As the crank 372 begins to rotate under the influence of the driving mechanism, the device 344 first descends, forcing the projections 346 into the sole. These are locked therein to hold it firmly in place, and the continued rotation of the crank reverses the movement of 40 the transfer mechanism, causing it to swing upwardly and inwardly toward the turret until it assumes the position illustrated in dotted lines in Fig. 13. This transferring travel is in synchronism with the action of the associated operating mechanism. It should be noted, and this remark applies to other transferring mechanisms hereinafter 45 described, that the carrying of a sole from the magazine to a support is effected by a parallel motion, and that during the entire movement said sole is maintained horizontal, as it was in its container, reducing the liability to accidental release, and that, moreover, the oscillation of the transferring mechanism in a vertical plane minimizes the space occupied circumferentially of the turret and thus avoids interference between adjacent mechanisms. Now the sole is in proximity to the surface of the support 60, at which time the release-lever 348 contacts with the tripping projection 350, freeing the sole-engaging 50 projections and causing the sole to be deposited upon the support. When thus de- 55 posited, the pin 108 has been forced downwardly, this having been effectively accomplished by vertical alinement of the transfer device 344 with the pin, and the pin 64 has entered the opening 6 in the sole. This latter action is facilitated by a pressure member 374, preferably of U-shape, and supported upon a vertical spindle 376 movable through an arm 378, the divided end of 60 which is clamped about a sleeve 380 fixed upon the spindle 349 of the transferring device. Between the contact member and the arm surrounding the spindle 376, is a spring 382, which permits the pressure member to yield as it forces the sole over the pin 64, 65 said sole being thus held until after the projections 346 are forced from it and it has been secured to the support by the gripping portion 96. To allow this vertical movement while holding the pressure member against turning, there is shown as rising from the arm a guide-projection 384, entering an opening in an arm projecting laterally from the upper end of the spindle. After the deposit 70 of the sole upon the support as just described, the crank 372 acts in its rotation to move the transferring device in the opposite direction, upwardly and outwardly to its initial position, ready for engagement with the succeeding sole fed from the container. The 75 depression of the pin 108 moves the roll 116 outwardly and raises the notched end of the latching-lever 100. The latter releases the lever 86, and the spring 98 carries the member 86 against the edge of the sole on the support, causing said sole to be gripped and retained by the portion 96 of the lever 94. 80

Operating position B—sole-cementing (Figs. 22 to 29, inclusive).

The sole having been placed upon the support at position A, the driving mechanism acts at the end of the predetermined operating interval, under control of the Geneva stop mechanism, to rotate the turret and the work-supports, the one under consideration passing to and coming to rest at position B. Into co-operation with the mechanism at position A an empty support is brought, while at the companion operating positions other actions 90 are taking place, each of which will be described in the order in which they occur. At this position B, at the outside of the support 95 rises from the base a standard 400. Between this and a ring 401 clamped upon the turret-standard 52 extend spaced rods 402, 402, furnishing a track, upon which is mounted to travel a carriage 404. Pivoted at 406 upon this carriage, for movement about a vertical axis, is a pot or receptacle 408 for the cement which is to be employed. For the present work, a mixture of equal parts of tar and pitch forms a suitable adhesive. At the inner, lower portion of the receptacle is an 100 inward extension 410, through which is a pas- 105

sage leading to a spraying or atomizing nozzle 412 having a vertical discharge-opening 414. The cement may be maintained in proper condition for delivery through the nozzle 5 by a heating device, consisting in the present instance of an electric unit 413 contained in a vertical opening through a boss projecting at the inner side of a casing 424, which carries the nozzle. The unit is supplied with current 10 by conductors 415, connected in the supply circuit in parallel with the unit 194 of the thermostatic device. Co-operating with the discharge-opening 414 within the nozzle is a valve 416 having a conical end portion 418 15 seated against a wall of the nozzle about the discharge-opening to close it, and also having a plurality of vertical grooves or passages 420 at the outside of the valve-body, these being, as illustrated, four in number, 20 through which the cement may flow when the valve is raised from its seat. Through the valve is also an axial passage 422, which is continued through a tube 423, carrying the valve and guided in the casing 424. This 25 tube extends above the casing and into a fitting 425. Within this fitting the tube carries a contact member 426, having through its lower portion a horizontal passage 428, and at its upper end a reduced portion extending 30 into an opening 430 in the fitting, where it may be moved into contact with a valve 432 held normally down to close the opening by a spring 434. Leading from the fitting 425 is a pipe 436, delivering pressure from the 35 air-tank 180. The cement-valve 416, and with it the air-valve 432, are governed by a rod 438, guided for vertical movement in bosses at the side of the casing 424 and connected to the tube 423 by an arm 440. A 40 spring 442, surrounding the rod 438 between one of the guiding bosses and a collar fast on the rod, holds the lower end of the latter down into contact with the upper surface of a square rod 446 guided at 448 upon forwardly 45 extended arms 449 of the carriage. Upon the cylindrical outer extremities of the rod 446 are mounted rotatable rolls 451, which are forced down into opposite recesses 450 formed at the upper sides of the guide-rods 50 402. When the rolls are thus seated in the recesses, the cement-valve 416 and the air-valve 432 are both closed. When the cement-container and nozzle are moved by the carriage, so that the rolls ride out of the recesses, 55 the rod 438 is lifted as the rolls contact with the upper surfaces of the rods, and both valves are opened. Since these rod-surfaces are shown in Fig. 24 of the drawings as horizontal, the valves, after being opened by a predetermined amount, will continue as thus 60 positioned, and will cause the air delivered through the opening 430 and passage 422 to draw down the cement from the container through the passages 420, and discharge it in a spray through the opening 414. If it be

desired to deliver the cement in varying quantities as the receptacle and nozzle travel, the rod surfaces may depart from horizontal lines, as illustrated at 453 in Fig. 26. By this arrangement, any desired quantity of cement may be ejected from the nozzle at any point in its travel. 70

The carriage 404 with the receptacle 408 is reciprocated to move the nozzle over the work by a link 454 articulated to the carriage and to a lever 456, 458 fulcrumed upon the standard 400. The upper section 456 of the lever is arranged to swing independently of the lower portion 458 between a yieldable stop 460 and an adjustable stop 462 carried upon opposite arms of a yoke 464, which may be integral with the lever-section 458. The position of the stop 462, which is in the form of a screw threaded through the yoke-arm, may be changed to vary the amount of lost motion between the mechanism actuating the lever and its connection to the carriage. Thus the distance traveled by the nozzle in delivering cement over the sole may be changed. The yield of the stop 460 permits the carriage to be brought back to a positive stop against the standard in its outward movement, while the motion of the actuating mechanism producing this continues to some extent. The lower extremity of the lever-section 458 is joined to an eccentric-rod 466 pivoted upon the strap of an eccentric 468 loosely mounted upon the shaft 154. Fulcrumed upon the hub of the eccentric is a lever 470, the inner end of which is turned down and forced by a spring 472, interposed between the opposite arm of the lever and a projection from the eccentric-hub, toward a circular series of depressions 474 in the upper surface of the gear 157 (Fig. 28). The lever is normally held disengaged from the gear-depressions by contact with it of a plunger 476, drawn down by a spring 478 into the path of the lever when it revolves. Formed upon the upper extremity of the plunger is an inclined surface 480, so related to the path of the roll 116 of the support, when said roll is in its outward position, as a result of the presence of a sole upon the support, that these elements will contact in the revolution of the roll, which rides under the surface 480, raising the plunger to free the lever 470. The downturned end thereupon enters one of the depressions in the gear 157, which is constantly rotating, thus transmitting this rotation to the eccentric, which acts to oscillate the lever 456, 458, and thereby reciprocate the receptacle, carrying the nozzle over the work. As the receptacle advances, the rolls 451 travel out of the depressions 450, the horizontal surfaces of the rods 402, by their contact with the rolls, raising the rod 438 to open the air and cement-valves, and start the application of the cement to the work. This occurs during the travel of the nozzle in both 80 85 90 95 100 105 110 115 120 125 130

directions, the discharge of cement ceasing only when the rolls 451 again enter the recesses.

Since it may not be desired to apply the cement along a straight line or one coinciding with a perpendicular to the rear edge of the sole, but rather to conform to the swing of the forepart, I have included means for moving the nozzle laterally, it turning with the receptacle about the pivot 406. From the nozzle, just above the surface of a forward portion 481 of the carriage, is a projection 482, guided by an overhanging lug 484 carried by the carriage to prevent lateral displacement of the receptacle in its movement. At one side of the projection 482 is a horizontal slide 485 operating in ways upon the carriage-portion 481, and having at its outer end a roll 486, movable in the travel of the carriage in contact with a cam-surface 487. The curvature of this surface is such as to direct the nozzle, as it swings with the receptacle, along the path corresponding to the portion of a sole, say that for a right shoe, which it is desired that the nozzle shall follow. This cam-surface is formed upon a bar 488, mounted upon a support 489 secured upon the rods 402 by set-screws 490. The bar 488 is preferably reversible, having a second cam-surface 491 at the side opposite the surface 487, this corresponding in contour to the portion of a left sole which is to be cemented. The mounting of the bar in its support is shown as consisting of a cylindrical portion, about which is a spring 492 acting to hold a pin 493 in engagement with either of two opposite slots formed in the support adjacent to the ends of the cam-surfaces. The yield of the spring 492 permits the bar 488 to be drawn to the right, as viewed in Fig. 23 of the drawings, whereupon it may be turned in either direction to bring the pin 493 into one or another of the slots. This positions either the cam-surface 487 or its associated surface 491 for contact with the roll 486 to adapt the mechanism for applying the cement to either a right or a left sole. Engaging a depression in the opposite side of the nozzle-projection 482 from the slide 485 is the rounded end of a rod 494 arranged to move through a bracket 495 rising from the carriage-portion 481. A spring 496 presses the end of the rod against the nozzle projection, to hold the latter in constant contact with the end of the slide 485 and thus to maintain the roll 486 in co-operation with the particular cam-surface which is at that time in use. A finger-piece 497, attached to or formed upon the rod 494, facilitates the retraction of the rod by the attendant to free the cam-bar 488 from the pressure of the roll 486, so that the desired cam-surface upon the bar may readily be brought into action. Whatever the adjustment of the cam-bar, the cement is applied over the area penetrated by the spurs 346, so

that they are sealed and are later entirely covered by the auxiliary sole-elements placed upon the cemented surface.

Operating position C—shank-piece-applying mechanism (Figs. 30 to 38, inclusive).

Following the cementing operation, the support, upon which the sole of which the assembling is being traced is mounted, is revolved to and stopped at position C. Here, upon a standard 500, is a multiple container for shank-pieces 5, which may consist of stampings of sheet steel, or other metal of the desired form. This container has a bearing in a short column 502 carried upon the top of the standard, there being stepped upon an anti-friction bearing 504 at the top of the column, a sleeve 506 journaled within the column, and having at its top a circular plate 508 furnishing the base of the container. Rising from this plate is a circumferential series of generally sector-shaped dividing walls 510, of which ten are here shown. These walls form between them ten parallel-walled spaces 512, best illustrated in Fig. 1. The spaces 512 receive elongated U-shaped holders 514, resting vertically between them, these holders being conveniently constructed of sheet metal, and each being closed at its outer side. Each holder is adapted to receive a stack of the shank-pieces, and may be filled conveniently outside the container, and then placed in position between the sectors, the shank-pieces being retained during this operation from falling through the bottom of the holder by short, inwardly curved flanges 516 at the bottom of its side walls. Passing through the container at its axis is a rod 518, surrounding and fixed upon which is a sleeve 520, having at its lower end, lying initially at the bottom of the holders 514, arms 522, of which there is one for each holder, similarly spaced about the axis of the container. Upon these arms rest the bottom shank-pieces of the stacks, the upper pieces being in close proximity to the tops of the holders.

The container is rotated to successively bring the holders into alignment with the support by spiral-gearing 524, connecting the sleeve 506 to a short shaft 526 journaled in a horizontal position upon the top of the standard 500. The shaft 526 is driven from a sectional main shaft 528, journaled in bearings upon the standards 52 and 500 at this position, through spur-gearing 530. The driven and driving gears of this pair 530 have respectively unbroken or toothless convex and concave portions 532, 532, which when in engagement stop the rotation of the shaft 526, and therefore of the container, interposing definite periods of rest between the periods of rotation when the teeth of the gears 530 are in contact. These intermittencies of rotation of the container give

time for the removal of the shank-pieces from their holders. Included between the sections of the shaft 528 is a clutch mechanism 584, which may be similar to that at position A, it being actuated by a rod 536 to cause the sections of the main shaft to turn together through a single rotation, lowered from its normally raised position by contact of the roll 116, as at position A, save that, as 19 was the case at position B, the roll is here held outwardly. The driven element of the clutch receives rotation through bevel-gearing 538 from a vertical shaft 540, which is driven by the sprocket-gearing 162, as has 25 already been described in connection with the general actuating mechanism of the machine. A crank 542 is formed upon the driven portion of the shaft 528, and reciprocates by means of a link 544, lever 546 and 30 sliding block 548, a vertical rack-bar 550. This bar is guided in a like manner to that of position A, and meshes with corresponding gear-segments 552, 555, turning upon shafts 554 projecting from the side of an upward 35 extension of the standard 500. Fixed upon the hubs of the segments are arms 556, to which is pivoted a bar 558, normally extending vertically above the particular container-holder which may be aligned with the 40 work-support at this position. Carried upon the lower extremity of the bar 558 is a shank-piece-picking or transferring device 560. This device may be as set forth in United States Letters Patent No. 1,438,480, 45 issued December 12, 1922, on application of Frederick M. Furber, including a pair of yieldable jaws 562, which are separated to seize and release the pieces by pressure directly upon them, though any other suitable 50 arrangement may be employed. From the initial position shown in full lines in Fig. 30 of the drawings, the picking device 560 is first lowered under the influence of the crank 542 to grasp the upper shank-piece in the holder beneath it, and is then carried upwardly and inwardly to the position appearing in dotted lines in the same figure, releasing the shank-piece held when this comes in contact with the sole. The crank 55 mechanism then returns the picker to its normal position.

It may be preferable to deposit the shank-pieces upon the soles with the axes of these co-operating elements generally coinciding, or it 55 may be desired to shift the pieces to the right or left of the center line of the soles when these are respectively rights or lefts. To allow this to be done, the arms 556 with their segments are movable longitudinally upon the shafts 554, and are provided with short arms 564, having turning upon them rolls 566 60 contacting with tracks 568. These tracks are formed in members 570, fixed upon the upper and lower extremities of a rod 572 mounted to turn in a bracket 574 projecting from the in-

ner side of the standard-extension. The rod is not only capable of turning in the bracket, but may move somewhat longitudinally against a spring 576 interposed between the upper member 570 and the hub of an arm 578 75 projecting horizontally from the rod. At the outer end of the arm is a vertical projection 580, which may engage any one of three depressions in the upper face of the bracket. These depressions are so related that when the arm-projection is in that at the center, the tracks 568 act upon the rolls 566 to guide the picker device in a plane coinciding with the longitudinal axis of the sole-support. Transfer of the projection to either the right or left 80 depression turns the rod through an angle, swinging the tracks 568, so that now the picker device in its movement is carried laterally to one side or the other, whereby it is caused to deposit the shank-piece in a position on the sole which will more nearly conform to either a right or left swing of its forepart.

In addition to being rotated to present successive holders to the device 560, the arms 522 are gradually elevated to compensate for each 90 layer of shank-pieces removed. The rod 518 has a tubular extension 581, extending downwardly from the container loosely about a rod 582 fixed at its lower end against movement upon a bracket 583 projecting from the side of the standard 500. Held against turning upon the lower extremity of the tube 581, by screws 584 projecting at their inner ends into short vertical slots in said tube, is a casing 585, shown as of generally frusto-conical form and closed at its bottom by a plate 586 having an axial opening to receive the rod 582. The movement of the casing upon the tube may be variably limited by a collar 587, fixed by a set-screw upon the tube. Engaging the thread of the rod within the casing is a frusto-conical nut 588, divided at 589 into three sections. The nut is connected to the casing with a capability for limited movement longitudinally with respect thereto, by pins 590, one for each 100 nut section, entering vertical slots in the casing-walls. Between the sections, with their ends seated in opposite recesses therein, are helical springs 592, exerting a force tending to separate the nut-sections and to move their outer inclined surfaces into contact with a corresponding surface upon the interior of the casing. These co-operating surfaces are held normally together by a spring 593, situated between the bottom of the casing and the nut, into a circular groove in the under side of the sections of which it extends. As the container is rotated by the gearing 524, the nut 588, turning with it under the influence of the casing connected to the tube 581, which tube is compelled to rotate with the container by contact of the arms 522 with the walls 510, is caused to travel up the thread of the stationary rod 582. The pitch of the thread of this rod is preferably equal to the thickness of 110 115 120 125 130

the shank-pieces to be applied to the soles. Therefore, after a circumferential series of shank-pieces has been taken by the picking mechanism from the top of all the holders, the 5 arms 522 will have been elevated to a distance equal to the thickness of a shank-piece. Consequently, upon the succeeding rotation of the container, the picking mechanism will find the shank-pieces at precisely the same level as 10 the preceding series. This continues throughout the rotation of the container, each shank-piece gradually ascending, by a helical movement, to its point of engagement by the picker mechanism. When all the shank-pieces have 15 been taken from the container-holders, the arms 522 should be returned to the bottom of the holders to support fresh stacks of shank-pieces. This may readily be accomplished by manually lifting the casing 585. When this is 20 done, the ends of the screws 584 travel up the slots in the tube 581 until this movement is arrested by contact with the collar 587. This tends to carry the inner wall of the casing away from the nut-sections 588, but the latter are 25 caused to follow under the influence of the spring 593, and are expanded by the springs 592. The sections are therefore caused to move radially from the rod 582 until the thread of the nut is disengaged from that of 30 the rod. When thus released, the tube and connected arms drop, bringing the latter into their initial position in proximity to the plate 508 of the container. Release of the casing by 35 the attendant causes the pressure of its interior wall upon the nut-sections to restore the engagement between them and the rod. The thread upon this rod is preferably formed with a flat upper face to adapt it to well resist any shocks which may be occasioned by the 40 stopping of the descent of the arms and associated movable parts.

To insure the maintenance of the applied cement in a proper condition to adhere to the filler-piece which is to be applied at position 45 D, there may be mounted upon the standard 52, at position C, an electric or other heating device 591. This device may consist of a plate containing the necessary heating units, joined in parallel to the supply-circuit, the 50 lower surface of the plate being just above the path of the soles carried by the supports 60, and it extending as far over the cemented areas as is possible without interfering with the application of the shank-pieces. By this 55 means, the cement upon a sole stopped at position C to receive its shank-piece is kept warm and plastic, and therefore in condition for the application of the filler-piece at position D and the subsequent pressing together of the 60 composite sole.

To facilitate the adhesion of the shank-pieces to the cemented surfaces of the soles S and to the fillers which are to be applied at the next position, they are preferably heated 65 in the container. This I have shown as ac-

complished by electric units 594, situated in vertical recesses in the walls 510, so that the heat generated is applied at both sides of all the shank-piece-receptacles. The conductors 595 of these units are joined in parallel to a 70 pair of collector-rings 596, 596 mounted upon an insulating block 597 fixed beneath the container-head 508. With these collector-rings contact a pair of brushes 598, 598, insulated from each other and from the column 502, 75 upon which they are carried, and connected to conductors 599 of the supply-circuit in parallel with the unit 194 of the thermostatic device.

Operating position D—filler-applying and 80 work-pressing mechanisms (Figs. 39 to 44, inclusive).

Rotation of the turret now brings the support to position D, at which there is to be applied over the heated shank held upon the cemented sole, a filler-piece, which will later occupy the space within the edges of an upper when this and the sole are brought into association. This filler-piece may be of a 85 plurality of layers of some such absorbent material as paper, impregnated with the asphaltum or other substance which is more or less solid under temperatures of the air, but may be made plastic by the application of heat. 90 Its form may be as illustrated at f in Fig. 42 (Sheet 17); it having a gage-opening o, similar to that in the sole to receive the support-pin 64. These filler-pieces are carried in a stack at the top of a standard 600 rising from 95 the base opposite the support at position D. They are shown as being held in a magazine or container 602, tubular in form and substantially conforming in transverse section to the external contour of the filler-pieces. The 100 magazines are preferably made up of sheet metal walls retained between inner and outer posts 604 and 606 projecting above the standard. The inner edge of the container has a projection 608 from both walls engaging 105 the post 604. The opposite ends of the walls have independent flanges 610, 610, so held in post 606 that they may be separated by wedges 612, 612 carried at different vertical positions upon a bar 614 arranged to be 110 moved toward and from the container by a cam-lever 616 fulcrumed upon the post 606. When the container is removed from between the posts, the spring of its walls brings the flanges 610 into close proximity with each 115 other, so that the opposite container-walls bear with some force upon the edges of the filler-pieces to hold these by frictional engagement within the container. When the container is in place between its posts, and the lever 616 is shifted the wedges 612, entering between the flanges 610, separate these 120 and move somewhat apart the opposite container-walls, so that the filler-pieces are freed from the retaining engagement and are left 125 130

free to descend by gravity through the container. The posts 604 and 606 may be provided respectively with hinged upward extensions 618 and 620, releasably held in a vertical position in alignment with the posts by latches 622, 622. When the latches are freed, the extensions may be swung outwardly to permit to be placed between them, in alignment with the main container 602, an auxiliary container 624, which may be generally similar to the main container. Upon the inner edge of the post-extension 620 is shown a wedge 626, which, when the extension is latched in place with its companion 618 to retain the container, enters between the separable flanges to free the filler-pieces and cause them to move downwardly through it and into the main container as the filler-pieces are taken from the latter. The bottom of the container 602 rests upon ledges above the top of the standard, and below it is guided in suitable ways in said standard and extended into horizontal projections 628 therefrom, a reciprocatory delivery plate 630. In this plate, in normal alignment with the filler-pieces in the container 602, is a depression substantially conforming to said filler-pieces, and into which the lowest one falls. The plate 630 is reciprocated by engagement with a rack 632 depending from its under side, of a gear 634 rotatable within the standard. Mounted to turn with the gear is a pinion 636 meshing with a segmental gear 638, also journaled in the interior of the standard. This segmental gear engages rack-teeth 640 upon a bar 642 guided for vertical movement within the standard. A connecting rod 644 unites this bar to a crank 646 upon the driven portion of a sectional shaft 648 rotatable in bearings upon the standards 52 and 600. The driving portion of the shaft 648 is rotated by the gearing 172 from motor 164. To it is connected by bevel-gearing 647 a vertical shaft 649 arranged to turn in the standard 52, from which power is transmitted by sprocket-gearing 174 to the operating mechanism at position E. Clutch mechanism 650 is interposed between the sections of the shaft 648, this in no essential respect differing from that described at other positions, and being controlled by a similar rod 652 having an inclined surface depressed by the roll 116. For each revolution of the crank 646, the plate 630 moves forward from beneath the container 602 carrying with it the filler-piece which lies within its depression into a definite vertical relation with the support 60, which is at that time at position D, ready for action upon it by the mechanism which will now be described. During this excursion of the plate, the succeeding filler-piece of the stack is temporarily held above the plane of the plate-depression by an extension 653 at the outer edge of the plate.

Extending above the support 60 at position

D, mounted at its opposite ends upon the standards 52 and 600, is a bar 654, through which is movable a rod 656 having fixed upon it a piston 658 operating within a cylinder 660 secured upon the upper side of the bar 654. A spring 662 surrounds the rod between the piston and bar to hold said piston in proximity to the upper head of the cylinder. Fastened to the lower end of the rod 656, and lying longitudinally of the support, is a carrier-bar 664, guided against turning in a horizontal plane by a rod 665 projecting through an opening in the bar 654. The carrier-bar has pivoted at 666 upon its outer end a pressure member 668, the opposite sides of which conform to the opposite sole-supporting surfaces of the member 60. The inner end of the pressure member is held normally above the path of the plate 630 by a latch 670 pivoted upon the carrier-bar and held in locking engagement with the pressure member by a spring 672. The latch may be released to bring about engagement between the pressure member and the filler-piece held in the plate-depression by a projection 674 upon the plate, which, as the plate reaches its extreme inward position, strikes a contact-screw 676 threaded horizontally through the lower end of the latch. By altering the position of this screw, the time of release of the pressure member may be brought into the correct relation with the extreme advance of the plate. The downward swinging movement of the pressure member about its pivot 666 after release by the latch occurs at a high rate of speed under the influence of a spring 677 interposed between the carrier-bar 664 and said pressure member. The travel of the member under the influence of the spring may be stopped by a shoulder 678 formed upon a depending portion of the carrier-bar. When thus stopped, engaging projections or spurs 680, 680, which are shown as separated from each other at its lowest portion and along its longitudinal axis; have been forced into the filler-piece, preferably without passing through it. This occurs just as the crank 644 reverses the travel of the plate, the spurs holding the filler-piece so that it passes out of the open inner end of the plate-depression, and remains hanging upon the spurs in the same vertical alignment to the sole to which it is to be applied, as determined by the forward position of the plate 630, while said plate travels back beneath the container 602 to receive another filler-piece. Now fluid pressure from the tank 180 is applied through a pipe 681 to the cylinder 660. The pressure in this pipe is preferably controlled by a rotatable valve 682 contained within a casing 683 situated adjacent to the shaft 540 at position C (Fig. 30). Referring particularly to Fig. 44 (Sheet 1), the valve contains a passage 684 with the openings through the valve-wall so spaced that they may be brought into

- simultaneous alinement with the two connections of the pipe 681 to the casing. The valve also contains a passage 685 for the purpose of connecting the outlet or delivery-portion 5 of the pipe 681 with a relief-opening 696 through the wall of the casing. Connection between the relief-opening and the supply-pipe takes place during the cutting off of communication between the pipe-sections and 10 permits the exhausting of the cylinder 660 during the elevation of its piston by the spring 662. The valve is held so that the pipe 681 is normally closed but with the relief connection open, by a torsion spring 686 acting 15 upon the valve-stem. The valve may be opened, that is, the sections of the pipe 681 connected, by a lever 687 fixed upon the valve-spindle and arranged to receive the contact of a roll 688 mounted upon a projection from 20 the shaft 540. At the proper period in the rotation of the shaft 540 to give the correct time relation between the filler-piece-transferring movement and the application of pneumatic pressure, the roll 688 shifts the 25 lever 687 to open the connection from the tank 180 to the cylinder 660. Thereupon the piston 658 descends, moving the pressure member 668 with the filler-piece carried upon its spurs toward the sole upon the support 60. 30 When the filler-piece strikes the sole, the pressure member is first swung about its pivot through a small arc until it contacts with a shoulder 689 upon the carrier-bar 664, which corresponds to its latched-up position. The 35 pressure is then exerted to force together the filler-piece, shank-piece and cemented sole, and since the cement is still warm and the shank-piece is heated, and moreover, as the filler-piece contains a substance softened by 40 heat, the three elements are firmly joined into a composite sole element, ready for application to a lasted upper. It is to be observed that since the filler-piece is advanced by the feed-plate into correct alinement with the 45 position which it is to occupy upon the sole, and since it is there applied to the pressure member which bears a nearly constant relation to the support, when said pressure member and support co-operate the filler-piece is 50 accurately located upon the sole.
- To warn the attendant when the container requires an additional supply of filler-pieces, the lower portion 602 is shown as containing a slot in its wall, through which may pass 55 a contact-finger 690, mounted upon a tilting carrier 691 movable upon a bracket 692. A spring 693 holds the finger with its end normally within the container to contact with the pieces therein. Mounted in proximity to the carrier are terminals 694, 694 of an alarm-circuit 695. When there are soles in the container at the level of the finger 690, the carrier is thereby held away from the terminals 694. When, however, the soles as used descend below the plane of the inner extremity 60 of the finger, the spring 693 acts to swing the carrier, so that it contacts with the terminals to close the circuit. This may contain any suitable indicating device, as a bell, upon hearing which the operator may remove 70 the empty auxiliary magazine 624 and replace it with one containing a supply of filler-pieces.
- Operating position E—work-removing mechanism (Figs. 45 to 48, inclusive).* 75
- At E, the last position of the machine, the travel of the support bearing the completed composite sole is stopped opposite a standard 700 having extending across its top a table 702 supporting a series of sole-receiving boxes or magazines 704, which are to be successively advanced into alinement with the support 60 as preceding magazines are filled with soles taken from said support. Each of 80 these magazines is shown as having a bottom wall and vertical inner end and side walls, the outer end being open, save for a block 706 carried upon the bottom of the magazine and upon which the rear portions of the soles 85 are supported to maintain them in proper position for transfer. Upon a bracket 708 opposite the receiving position is mounted a vertical bar 710 to retain the work during its delivery to the magazine. To permit of this 90 bar being adjusted for different lengths of soles, it is variably held by a screw 712 passing through a slot in an angular support, which forms a part of the bar, and being threaded into the bracket 708. The transfer of the soles one by one from the support 60 to the magazines is effected by a work-grasping device 714, which may be that made the subject of United States Letters Patents 95 No. 1,438,482, issued December 12, 1922, on application of Frederick M. Furber. This device is carried upon a bar 716, and has normally separated fingers 718 forced beneath the sole by contact of a portion 720 with the upper surface, and latched in this grasping position by a member 722. This latch may be released by a contact member 724. The carrier-bar 716 is oscillated to move the grasping fingers down into contact with the work upon the support 60, and then upwardly 100 and outwardly to a point over the magazine alined with the support to deliver it, by supporting arms and actuating gearing and connections 726, which may be identical with the corresponding parts at position A. In the 105 delivery position, the contact member 724 strikes what is at that time the upper side of the adjacent supporting arm, releasing the grasping fingers, which open to free the sole. The actuating connections receive motion 110 from a crank 728 upon one section of a driving shaft 730 extending between bearings on the standard 52 and standard 700. This shaft 730 is rotated through a vertical shaft 732 and bevel-gearing 734 by the sprocket- 115
- 120
- 125
- 130

gearing 174 connecting to position D. A clutch 736 included in the shaft 730 is controlled similarly to the like clutches at the other positions by a bar 738 forced down when the support arrives at position E by its roll 116 in its outward position. In preparation for this transfer of the sole, the toe-retaining device of the support is released by contact of the roll 118 with a cam-surface, furnished by a member 740 mounted upon the standard 52. This surface, with which the outer face of the roll contacts, draws the lever 80 inwardly until its stud 104 is at the inner side of a vertical line through the engaging end 102 of the latching lever 100. This withdraws the slide 86 from contact with the edge of the sole, and releases the retaining member 96, so that the completed sole is free to be taken from the support. The cam-surface holds back the lever 80, while the crank mechanism forces down the grasping device upon the sole, and when said sole is lifted from the support in its transfer to the magazine and frees the pin 108, the latching lever 100 tilts upon its fulcrum in an anti-clockwise direction, as viewed in Fig. 12 of the drawings, the left-hand end over-balancing the opposite extremity and overcoming the resistance of the elements associated therewith. This brings the recess 102 of the lever 100 into horizontal alinement with the stud 104, so that when the lever 80 is released by the passage of the roll 118 past the cam-surface, the stud enters the notch, latching the retaining device back in preparation for its co-operation with the next sole. At the same time, the lever 100 raises the pin 108 above the surface of the support, and draws the roll 116 back into its initial position.

Through a slot in the table 702 operates a sprocket-chain 742, running over sprocket-wheels 744, one only of these wheels being illustrated, and this being shown particularly in Fig. 47. Upon the chain are rounded projections 746, spaced from one another by distances equal to the widths of the magazines, so that said magazines resting upon the table are moved over it by engagement of the projections when the chain is actuated. Upon the shaft of the sprocket-wheel 744 is a gear 748 meshing with a pinion 750 upon a shaft 752 journaled horizontally beneath the table and within the standard 700. A pinion 754 is fixed to a sleeve 755 upon a spindle 756 fixed in the standard in alinement with the shaft 752 and having meshing with it a rack-bar 758 guided for vertical movement in a bracket 759 depending from the table 702 within the standard. Upon the adjacent ends of the sleeve 755 and shaft 752, respectively, are ratchet-wheels 760 and 762, the latter of which is of less diameter than its companion. The ratchet-wheel 760

with the fixed spindle 756, preventing it from turning in one direction while leaving it free in the other. The ratchet-wheel 762 is fast upon its shaft. Both these wheels have the same number of teeth, and the wheel 760 has a toothed space 766, which is deeper than the other teeth of the same wheel, extending inwardly to the same extent as do the teeth of the wheel 762. Fixed upon the sleeve 755 is an arm 768, having pivoted at its outer extremity a pawl 770 extending over the ratchet-teeth of both wheels. Projecting from one side of the pawl is a pin 772, entering a slot in an arm 774 movable with some frictional resistance about the hub of the wheel 762. This slot is inclined with respect to tangents to the ratchet-wheels at points in a radial plane extending through the pin and the axis of the shafts, the inclination of this slot being outwardly, as referred to the direction of the idle movement of the pawl. The effect of this arrangement is that during such idle movement, the slot, acting upon the pin, lifts the pawl out of engagement with the ratchet-teeth, so that there is no unnecessary contact during this movement. On the reverse or wheel-actuating movement, the slot brings the pawl back into engagement with the teeth, the arm 774 then slipping over the hub of the wheel 762. The upper extremity of the rack-bar 758 is joined by a link 775 to the connections 726 of the carrier-bar 716, so that during the oscillation of the bar in the transfer of the work from the support to the magazines, the rack is reciprocated, and through the gear 754 turns the arm 768. The upward movement of the rack-bar is an idle one, the arm 768 carrying the pawl 770 over the ratchet-teeth held out of contact therewith by the co-operation of the pin 772 with its slot. At this time the wheel 760 is prevented from turning by the clutch device 764. Upon the reverse movement of the rack-bar, the pawl is carried into engagement with the teeth of the wheel 760 and turns it, the clutch device 764 now being free. The amount of revolution imparted by the rack-bar to the pawl about the ratchet-wheel is equal to 360 degrees plus the pitch of the teeth. Assuming that the pawl started at a tooth adjacent to the deep space 766, each actuation of the rack-bar consequently moves the pawl one space nearer to said deep space, so that after a number of bar actuations corresponding to the number of teeth about the wheels, the pawl will reach the space 766, and, entering it, will become effective to drive the wheel 762, rotating it. This will, through the gearing 748, 750, turn the sprocket-wheel 744 and cause the travel of the chain, the full throw of the pawl at this time being sufficient to move the chain to advance the magazine in the receiving position forwardly upon the table, where it may be released from

the chain, and to bring the next magazine opposite the support. The number of teeth in each ratchet should correspond to the number of soles which it is desired each magazine shall contain, so that this bringing forward of a fresh magazine will occur only after the preceding magazine has been filled.

To prevent the accidental displacement of the magazine which is being filled, it may be locked during practically the entire time, save when it is to be shifted. To this end, the hub of the gear 748 has a depression adapted to receive the angular end of a locking lever 776 fulcrumed beneath the table. A spring 778 exerts its force to draw the engaging end of the lever toward the hub-depression. The opposite arm of the lever 776 is joined by a link 780 to an arm 782, pivoted upon the guide member 759. Turning upon the end of the arm 782, and projecting into the path of an inclined surface 788 upon the lower end of the rack-bar, is a roll 786. The bar 758 is preferably made in sections, with an interposed spring 790, so that the portion carrying the rack and driving the magazine-shifting mechanism may yield. Its lower extremity adjacent to the contact surface 788 moves against a screw 791 threaded vertically through the end of the guide 759. When the surface 788 strikes the roll 786, it swings the arm 782 to the right (Fig. 48), and withdraws the engaging end of the lever 776 for an instant from the depression of the gear 748; then upon the upward movement of the rack-bar, quickly restores the engagement. The time of removal of the lever from the depression is such that when the bar makes its actuating stroke upon the entry of the pawl 770 into the deep space 766, the ratchet-gearing acts to turn the gearing 748 and 750 before the engagement of the lever 776 with its depression can be restored. Consequently, it falls upon the hub of the gear 748, riding thereon during the movement of the magazines, and when this has been completed, entering the depression to lock the newly alined magazine. Adjustment of the vertical position of the end of the screw 791 varies the time during which the rack-bar is effective upon its up-stroke to shift the magazines, the higher the screw, the more being the lost motion in the bar due to the compression and expansion of the spring. By this means, the length of travel of the magazines may be changed, so they will exactly aline with the support 60 for the reception of the completed soles.

Beyond position E there is supported upon the extension of the standard 700, a cam-surface 797 arranged to contact with the roll 78 of the work-support to press it upwardly, and beyond this a second cam-surface 798 for contact with the work-support roller 70, acting to move this inwardly. This last-mentioned cam-surface is connected to the stand-

ard by a slot-and-screw connection 799, which permits it to be adjusted toward and from the turret to vary the amount which the roll 70 by contact with it will move the slide 66 and the supported pin 64. After the work-support leaves position E, the roll 78, coming in contact with the cam-surface 797, swings the upper end of the lever 72 inwardly to unlock the slide 66. This leaves the work-gaging pin 64 free to be thrust outwardly by the spring 68, nullifying the setting which has been made for the work just operated on through its cycle, and preparing it for a new setting, which will be correct for the work to be acted upon during the next cycle. This having been accomplished, the roll 70 strikes the cam-surface 798. This will have been adjusted, if necessary, to produce the desired setting, and since at this time the lever 72 has been released by the surface 797, the slide 66 will be locked after the roll 70 has traveled by the surface 798. The pin 64 is therefore in position to receive the soles supplied at position A.

Outline of the operation of the machine.

There will now be given a brief summary of the action of the entire machine with reference to the elements more closely associated with the work, and the principal parts operating or controlling them.

To prepare the machine for its automatic action, the sole, shank-piece and filler-piece-containers at positons A, C and D, respectively, are filled, and cement placed in the receptacle 408 at position B. The motors 130 and 164 are started, and the supply-circuit closed for the heating units 413, 591 and 594 at positions B and C and the unit 194 associated with the thermostatic device 191 of the pneumatic system. When the heat generated by these units has become sufficient to render the cement at the nozzle 412 properly fluid and the shank-pieces *s* of a sufficient temperature, the unit 194 has so affected the thermostatic device that it closes the outlet-valve 190 from the air-supply pipe 181. The pump 182, which is being continuously driven whenever the motor 130 is in operation, thereupon acts to establish air pressure in the tank 180 and associated pipes. This pressure is ineffective until it is sufficient to raise the valve 187 from its seat. A sufficient predetermined actuating force being established, the piston 175 is moved by the air pressure to engage the main clutch 176 of the shaft of motor 130. This puts into operation the driving mechanism for the turret carrying the five work-supports 60, which moves with predetermined intervals of advance and rest under the control of the Geneva stop mechanism 150, 152, and also furnishes power for the operating mechanisms at positions A, B and C. The operating mechanisms at positions D and E have constantly available power when the

motor 164 is in operation. The operations occurring at each of the five positions will be followed for the work carried by a single support, bearing in mind the fact that in connection with each of the other four supports, operations are simultaneously occurring peculiar to the particular position at which each support is located.

A support entering position A without a sole upon its surface has had the lever 80 of the retaining device drawn back at the preceding position and latched by the lever 100, the pin 108 at the center of the support being projected above the receiving surface and the controlling roll 116 being at its inner position. The pin 64 for entering the openings *o* of the soles and filler-pieces has also been set adjacent to the preceding position by action upon its roll 70, and locked by the lever 72. This setting of the pin 64 is such as to provide automatically for the proper positioning of the size of soles which are in the sole-container. Just before the revolution of the support ceases at position A under the control of the Geneva stop mechanism, the roll 116 causes the actuation of the driving clutch 250 at this position. As a result of this, the transfer mechanism 344 engages a sole *S*, which has been advanced from the container by the slides 236 and 274, alined laterally by the co-operating effect of these slides and that numbered 284, with the assistance of the fingers 298, and adjusted into correct longitudinal relation by the toe-contact lever 300 operating with the gage-wall 340. The engaged sole is then conveyed by the movement of the transfer device to the support 60, where its pressure upon the pin 108 trips the latching lever 100, releasing the lever 80 and causing the retaining device carried by it to first move against and then grip the sole to fix it upon the support for the succeeding operations. The transfer device then swings back to its initial positon, and the support travels forward to position B.

If for any reason, as because the container at position A was empty, no sole has been placed upon the support, the pin 108 will not have been depressed, and the roll 116 will remain at its innermost position. It does not therefore strike the controlling means for the driving mechanism at position B, or any of the succeeding positions, and no operations occur until the defect has been corrected. But the sole being in place, and the roll 116 forced outwardly as a result, the controlling lever 470 of the driving mechanism at position B is freed to start the action. The cement-receptacle 408 is moved forward, carrying its nozzle along the surface of the sole to be cemented, the adhesive being sprayed through said nozzle when the valves 416 and 432, controlling the supply from the receptacle and pneumatic system respectively, are opened by the passage of the rolls 451 out

of the depressions which permit the closure of the valves. Previous adjustment of the cam-bar 488 provides for the proper disposition of the cement upon either right or left soles. The cement-receptacle having been 70 returned to normal by the driving mechanism, and the valves closed by the dropping of the rolls into the depressions, the support advances to position C.

Again the roll 116 starts the driving mechanism, causing the transfer device 562 to lift a shank-piece from the holder 514 which is positioned beneath it and carry it above and press it upon the cemented surface of the sole. During this transfer, the shank-piece-container is gradually rotated to bring the next holder under the influence of the transfer mechanism, the entire contents of the container being gradually raised by the screw 582 and nut 588 associated with the shank-piece-supporting arms 522 to elevate the stacks in the holders layer by layer to insure the proper engagement of the transfer device throughout the entire depth of the stacks. Whether it is desired to lay the shank-piece upon the sole in a central or neutral relation, or at one side or the other to more closely follow the center-line of a right or left sole, may be determined by a setting of the arm 578, with a consequent variation in the position of the transfer device-controlling tracks 568. While the progress of the work is arrested at this position, the cement delivered to it at position B is kept plastic by the heating device 591.

Upon the succeeding movement of the support to position D, the operating mechanism is thrown into action by the roll 116 to cause the feed-plate 630 to carry in its depression the lowest filler-piece *f* from the stack in the container 602 beneath the pressure member 668, the feed-plate there releasing the pressure member by co-operation with its latch 670, and causing the holding spurs 680 to enter and retain the filler-piece while the slide is withdrawn. Pressure from the pneumatic system is thereupon admitted to the cylinder 660 under the control of the valve 682, carrying the filler-piece upon the pressure member into contact with the sole and superposed shank-piece upon the support and forcing all three together to form the composite sole.

The assembling of the work pieces having now been completed, the support moves the finished article to position E, where it is grasped by the device 714, started into action by the roll 116, and is transferred to a magazine 704 and dropped therein. As a magazine is filled, it is automatically moved from its receiving position, and an empty magazine substituted by the sprocket connections 742, 744 and the ratchet mechanism 760, 762 and 770, the shifting mechanism being temporarily unlocked for this purpose by the lever 130

776 under the control of the actuating rack-bar 758. As the work-support leaves position E, its roll 78 encounters the cam-surface 797, unlocking the slide of the sole-receiving pin 64. This, in the further travel of the support, is set by the engagement of the slide roll 70 with the cam-surface 798, which will have been properly adjusted for the particular length of sole which is to be next operated upon. Having thus been located, the pin is locked by the now released lever 72, and the support is ready for the beginning of a new cycle at position A.

Having fully described my invention, what I claim as new and desire to secure by Letters Patent of the United States is:

1. In an assembling machine, a support, means movable in cooperation with the support for delivering an article to said support, means movable into contact with the article after its application to the support and while it is engaged by the delivering means to secure said article on the support, and means for applying another article to that upon the support.

2. In an assembling machine, a support, means for moving the support to different operating positions, means for delivering an article to the support in one position, means movable toward the support to secure said article thereon, means effective in another position of the support for applying another article to that upon the support, and means associated with still another position for releasing the securing means.

3. In an assembling machine, a support provided with a surface upon which an article may rest by gravity, means for laying an article on the support, means movable into contact with the upper side of the supported article and controlled by said article to secure it on the support, and means for applying another article to that upon the support.

4. In an assembling machine, a support, means for moving the support to different operating positions, means for delivering an article to the support in one position, means co-operating with the support to secure said article thereon, said securing means being controlled as a result of the movement of the support, and means effective in another position of the support for applying another article to that upon the support.

5. In an assembling machine, a support, means for moving the support to different operating positions, means for delivering an article to the support in one position, means co-operating with the support to secure said article thereon, said securing means being controlled by the article and in the movement of the support, and means effective in another position of the support for applying another article to that upon the support.

6. In an assembling machine, a support, means for moving the support to different op-

erating positions, means for delivering an article to the support in one position, means co-operating with the support to secure said article thereon, means movable with the support for effecting the engagement of the securing means, means effective in another position of the support for applying another article to that upon the support, and means for controlling the securing means, said controlling means acting under the influence of the support in its movement from the last-mentioned position.

7. In an assembling machine, a plurality of supports, means for moving the supports to successive operating positions, means for simultaneously delivering articles to the supports at different successive positions, one of said articles being applied directly to a support and another into co-operation with such article, and means for forcing the first-mentioned article against the support, said forcing means being arranged to maintain the article upon the support during the movement of the latter.

8. In an assembling machine, a plurality of supports, means for moving the supports to successive operating positions, means for delivering articles to the supports at such successive positions, means made effective in the first position for securing an article to the support, and means fixed against movement adjacent to the last position for releasing the securing means.

9. In an assembling machine, a plurality of supports, means for moving the supports to successive operating positions, means for delivering articles to the supports at such successive positions, one of said articles being applied directly to a support and another into co-operation with such article, and means movable by an article in the first position for causing the securing of the first-mentioned article to the support.

10. In an assembling machine, a plurality of supports, means for moving the supports to successive operating positions, means for delivering articles to the supports at such successive positions, one of said articles being applied directly to a support and another into co-operation with such article, means engaged by the article in the first position for causing the securing of the first-mentioned article to the support, and means associated with the last position and engaged by the securing means to release said securing means.

11. In an assembling machine, a plurality of supports, independent article-holding means situated at different operating positions, means for producing relative movement between the supports and holding means to bring about co-operation between the different holding means and supports, means for simultaneously transferring articles from the holding means to the supports, and means movable upon each support for securing

- thereto the first article only of the group transferred thereto, the succeeding articles of said group being delivered upon such first-secured article.
12. In an assembling machine, a plurality of supports, independent article-holding means situated at different operating positions, means for producing relative movement between the supports and holding means to bring about co-operation between the different holding means and supports, means for simultaneously transferring articles from the holding means to the supports, means for securing upon each support the first article of the group transferred thereto, and means common to the supports for releasing the securing means.
13. In a composite-sole-assembling machine, a support, a sole-container, means for transferring a sole from the container and placing its tread-surface in contact with the support, a container for auxiliary sole-portions, and means for elevating an auxiliary portion from the container and lowering it into contact with the sole upon the support, this last-mentioned transferring means being arranged to apply the auxiliary portion over an area spaced inwardly from the periphery of the sole.
14. In a composite-sole-assembling machine, a support, a sole-container, means for transferring a sole from the container to the support, a plurality of containers for auxiliary sole-portions, and means for successively transferring said auxiliary portions from each of their containers into contact with the sole and with one another.
15. In a composite-sole-assembling machine, a support, a sole-container, means for transferring a sole from the container to the support, means engaging the transferred sole to clamp it upon the support, a container for auxiliary sole-portions, and means for transferring said auxiliary portions from the container to the sole upon the support.
16. In a composite-sole-assembling machine, a support, means for causing the travel of the support to different positions, a sole-container at one position, mechanism at said position for transferring a sole from the container and placing its tread-surface in contact with the support, a container at a succeeding position for auxiliary sole-portions, and mechanism at this position for transferring an auxiliary portion from its container into contact with the shank-portion of the supported sole.
17. In a composite-sole-assembling machine, a support, a sole-container, means for transferring a sole from the container to the support, a member movable upon the support and controlled by contact with the sole to engage said sole to clamp it upon the support, a container for auxiliary sole-portions, and means for transferring said auxiliary portions from the container to the sole upon the support.
- means for transferring said auxiliary portions from the container to the sole upon the support.
18. In a composite-sole-assembling machine, a support, means for causing the travel of the support to different positions, a sole-container at one position, mechanism at said position for transferring the sole from the container to the support, a member movable upon the support to engage the sole to clamp it to the support and controlled in the movement of said support to effect the release of the clamped sole, a container at a succeeding position for auxiliary sole-portions, and mechanism at this position for transferring an auxiliary portion from its container to the supported sole.
19. In a composite-sole-assembling machine, a support, means for causing the travel of the support to different positions, a sole-container at one position, mechanism at said position for transferring the sole from the container to the support, a member movable upon the support and controlled by contact of the sole to engage the sole to clamp it to the support and controlled in the movement of said support to effect the release of the clamped sole, a container at a succeeding position for auxiliary sole-portions, and mechanism at this position for transferring an auxiliary portion from its container to the supported sole.
20. In a composite-sole-assembling machine, a rotatable turret, a plurality of supports fixed against movement upon the turret, means for intermittently rotating the turret to cause each support to occupy successive positions, mechanism at one position for applying a sole to each support, and mechanism at another position for applying an auxiliary sole-portion to the thus supported sole, the applying mechanisms being arranged to move toward and from the axis of the turret.
21. In a composite-sole-assembling machine, a standard, a rotatable turret journaled about the standard, a plurality of supports mounted upon the turret, a member movable upon each support for securing soles thereto, means for intermittently rotating the turret to cause each support to occupy successive positions, mechanism at one position for applying a sole to each support, and mechanism at another position for applying an auxiliary sole-portion to the thus supported sole.
22. In a composite-sole-assembling machine, a rotatable turret, a plurality of supports mounted upon the turret and maintained equidistant from the axis thereof, means for intermittently rotating the turret to cause each support to occupy successive positions, mechanism at one position for applying a sole to each support, mechanism at another position for applying an auxiliary sole-portion to the thus supported sole, and

- mechanism at the last position arranged to lift the composite sole from its support and convey it outside the turret. 65
23. In a composite-sole-assembling machine, a rotatable turret, a plurality of supports mounted upon the turret, a member movable upon each support for securing soles thereto, means for intermittently rotating the turret to cause each support to occupy successive positions, mechanism at one position for applying a sole to each support, the sole-securing means being actuated in the application of the sole, mechanism at another position for applying an auxiliary sole-portion to the thus supported sole, mechanism at the last position for removing the composite sole from its support, and means acting before the support reaches the last position for releasing the securing member. 70
24. In a composite-sole-assembling machine, a rotatable turret, a plurality of supports mounted upon the turret and symmetrically arranged about the axis of rotation, means for intermittently rotating the turret to cause each support to occupy successive positions corresponding in arrangement to the supports, containers situated outside the periphery of the turret at different positions and organized to hold various elements of a composite sole, and means movable radially of the turret for simultaneously transferring the elements from the containers to the supports. 75
25. In a composite-sole-assembling machine, a rotatable turret, a plurality of supports mounted upon the turret, means for intermittently rotating the turret to cause each support to occupy successive positions, containers at different positions for various elements of a composite sole, means for simultaneously transferring the elements from the containers to the supports, and a clamping device associated with each support and arranged to secure thereto the sole-element first transferred. 80
26. In a composite-sole-assembling machine, a rotatable turret, a plurality of supports mounted upon the turret, means for intermittently rotating the turret to cause each support to occupy successive positions, containers at different positions for various elements of a composite sole, means for simultaneously transferring the elements from the containers to the supports, a clamping device associated with each support and arranged to secure thereto the sole-element first transferred, and means arranged for contact with such sole-element to initiate the clamping action. 85
27. In a composite-sole-assembling machine, a rotatable turret, a plurality of supports mounted upon the turret, means for intermittently rotating the turret to cause each support to occupy successive positions, con- tainers at different positions for various elements of a composite sole, means for simultaneously transferring the elements from the containers to the supports, a clamping device associated with each support and arranged to secure thereto the sole-element first transferred, means arranged for contact with such sole-element to initiate the clamping action, and a contact member acting upon the clamping device in the rotation of the turret for effecting the release of the sole-element. 90
28. In an assembling machine, a traveling support, means for delivering an article to the support, means movable across the surface of the support for distributing a coating of adhesive over the article thereon, and means for applying another article to the coated surface while the first-mentioned article is in place upon the support. 95
29. In an assembling machine, a support, means for delivering an article to the support, means for securing the delivered article upon the support, means for applying a coating of adhesive to the secured article, and means for applying another article to the coated surface while the first mentioned article is still secured upon the support. 100
30. In an assembling machine, a support, means for delivering an article to the support, means for securing the delivered article upon the support, means for applying a coating of adhesive to the secured article, means arranged to change the area to which the adhesive is applied, and means for applying another article to the coated surface. 105
31. In an assembling machine, a support, means for delivering an article to the support, means for securing the delivered article upon the support, means for applying a coating of adhesive to the secured article, means arranged to change the angle at which the applying means acts upon the article, and means for applying another article to the coated surface. 110
32. In an assembling machine, a plurality of supports, means for moving the supports to successive operating positions, means for delivering articles to the supports at such successive positions, one of said articles being applied directly to the support and another into co-operation with such article, means movable to secure the first-mentioned article to the support, and means for applying to the secured article at an intermediate position a means for maintaining an association of the articles. 115
33. In an assembling machine, a plurality of supports, means for moving the supports to successive operating positions, means for delivering articles to the supports at such successive positions, one of said articles being applied directly to the support and another into co-operation with such article, pressure means for securing the first-mentioned article to the support. 120
- 125

article to the support, and means for applying an adhesive to the secured article at an intermediate position.

34. In a machine of the class described, 5 an article-container, a work-support, a device having projections arranged to enter and be withdrawn from the article, means for moving the device to effect the transfer of an article from the container to the support, an adhesive container and means for delivering adhesive from the container and applying a coating to the article over the area entered by the projections, after their withdrawal.

10 35. In a machine of the class described, an article-container, a work-support, a device having projections arranged to enter and be withdrawn from the article, means for moving the device to effect the transfer of an article from the container to the support, 15 means for applying a coating of adhesive to the article over the area entered by the projections, after their withdrawal, and means for applying another article to the coated area.

20 36. In a composite-sole-assembling machine, a traveling support, means for moving the support intermittently, a sole-container, mechanism for transferring a sole from the container to the support, a cement-receptacle, 25 and mechanism for delivering cement from the receptacle to the sole during an intermittence of travel of the support.

30 37. In a composite-sole-assembling machine, a support, a sole-container, mechanism for transferring a sole from the container to the support, a cement-receptacle, mechanism for delivering cement from the receptacle to the sole upon the support, means for retaining the sole upon the support during the cementing operation, a container for auxiliary sole-portions, and mechanism for transferring an auxiliary portion from its container to the cemented surface while the sole is under the influence of the retaining means.

40 38. In a composite-sole-assembling machine, a support, means for causing the travel of the support to different positions, a sole-container at one position, mechanism at said position for transferring a sole from the container to the support, a cement-receptacle at another position, mechanism for delivering cement from the receptacle to the sole upon the support, a container at a succeeding-position for auxiliary sole-portions, and mechanism at this position for transferring an auxiliary portion from its container to the cemented sole.

45 39. In a composite-sole-assembling machine, a rotatable turret, a plurality of supports mounted upon the turret, means for intermittently rotating the turret to cause each support to occupy successive positions, a sole-container at one position, mechanism for transferring the soles from the container to the supports, a cement-receptacle at another

position, and mechanism for delivering cement from the receptacle to the supported soles.

50 40. In a composite-sole-assembling machine, a support, a sole-container, means for transferring a sole from the container to the support, a cement-receptacle, mechanism for delivering cement from the receptacle to the sole upon the support, and means arranged to vary the application of cement according to whether a right or left sole is operated on.

55 41. In a composite-sole-assembling machine, a support, a sole-container, means for transferring a sole from the container to the support, a cement-receptacle, mechanism for delivering cement from the receptacle to the sole upon the support, and means arranged to vary the action of the cement-applying means to correspond to a right or left sole.

60 42. In an assembling machine, a traveling support, means for bringing pieces of material and assembling them upon the support at successive steps in its travel, and means acting prior to its advance to the support for heating a piece of the material.

65 43. In an assembling machine, a traveling support, means for delivering a piece of material to the support, means for heating another piece of material, and means for placing the heated piece upon that advanced by the support in its travel.

70 44. In an assembling machine, an article-support, means for delivering a piece of material to the support, a container for a stack of pieces of material, means extending longitudinally of the stack for heating the container, and means for transferring a piece from the container to that carried by the support.

75 45. In an assembling machine, an article-support, means for delivering an article to the support, means for securing the article to the support, a container for articles, means for heating the container, and means for transferring an article from the container to an article secured upon the support.

80 46. In an assembling machine, a plurality of supports, means for moving the supports to successive operating positions, means for delivering articles to the supports at such successive positions, and means at one of the positions for heating the articles thereat.

85 47. In an assembling machine, a plurality of supports, independent article-holding means situated at different operating positions, means for heating one of the article-holding means, means for producing relative movement between the supports and holding means to bring about co-operation between the different holding means and supports, and means for simultaneously transferring articles from the holding means to the supports.

90 48. In an assembling machine, a support, means for delivering an article to the support,

- means for applying a coating of adhesive to the article upon the support, means for applying another article to the coated surface, and means for heating the last-mentioned article.
5. 49. In an assembling machine, a support, means for bringing articles together upon the support in unvarying order, and means acting prior to their assemblage to change the relation in which the articles are to be assembled.
5. 50. In an assembling machine, an article-support, means for delivering an article to the support, a container for articles, means for transferring an article from the container to the support, and means arranged for control by the operator to modify the transferring movement transversely of its path to change the relation of the transferred article to the support.
20. 51. In an assembling machine, a support, means for delivering an article to the support, means for applying a coating of adhesive to the delivered article, means arranged to change the area to which the adhesive is applied, means for applying another article to the coated surface, and means arranged to change the area upon which the second article is applied.
30. 52. In an assembling machine, a support, means for delivering an article to the support, means for applying a coating of adhesive extending longitudinally of the delivered article, means arranged to change the angle at which the applying member acts upon the article, means for applying another article to the coated surface, and means arranged to change the transverse position in which the second article is placed upon the coated surface.
40. 53. In a composite-sole-assembling machine, a support, a sole-container, means for transferring a sole from the container to the support, a shank-piece-container, and means for transferring a shank-piece from said container to the supported sole.
50. 54. In a composite-sole-assembling machine, a support, a sole-container, means for transferring a sole from the container to the support, a cement-receptacle, mechanism for delivering cement from the receptacle to the sole upon the support, a shank-piece-container, and means for transferring a shank-piece from its container to the cemented surface.
55. 55. In a composite-sole-assembling machine, a rotatable turret, a plurality of supports mounted upon the turret, means for intermittently rotating the turret to cause each support to occupy successive positions, a sole-container at one position, mechanism for transferring the soles from the container to the supports, a cement-receptacle at another position, mechanism for delivering cement from the receptacle to the supported soles, a container for auxiliary sole-portions at still another position, mechanism for transferring auxiliary portions to the cemented areas, and a device at the last-mentioned position for heating the auxiliary portions.
5. 56. In a composite-sole-assembling machine, a rotatable turret, a plurality of supports mounted upon the turret, means for intermittently rotating the turret to cause each support to occupy successive positions, a sole-container at one position, mechanism for transferring the soles from the container to the supports, a shank-piece-container at another position, and mechanism for transferring shank-pieces from their container to the supported soles.
15. 57. In a composite-sole-assembling machine, a rotatable turret, a plurality of supports mounted upon the turret, means for intermittently rotating the turret to cause each support to occupy successive positions, a sole-container at one position, mechanism for transferring the soles from the container to the supports, a cement-receptacle at another position, mechanism for delivering cement from the receptacle to the supported soles, a shank-piece container at another position, and mechanism for transferring shank-pieces from their container to the cemented areas.
25. 58. In a composite-sole-assembling machine, a support, a sole-container, means for transferring a sole from the container to the support, a cement-receptacle, mechanism for delivering cement from the receptacle to the sole upon the support, a shank-piece-container, means for transferring a shank-piece from its container to the cemented surface, and a device for heating the shank-pieces.
35. 59. In a composite-sole-assembling machine, a support, a sole-container, means for transferring a sole from the container to the support, a cement-receptacle, mechanism for delivering cement from the receptacle to the sole upon the support, a shank-piece-container, a device arranged to heat the container, and means for transferring a shank-piece from its container to the cemented surface.
45. 60. In a composite-sole-assembling machine, a rotatable turret, a plurality of supports mounted upon the turret, means for intermittently rotating the turret to cause each support to occupy successive positions, mechanism at one position for applying a sole to each support, mechanism at another position for applying an auxiliary portion to the thus supported soles, and a device at the last-mentioned position for heating the auxiliary portion.
55. 61. In a composite-sole-assembling machine, a support, a sole-container, means for transferring a sole from the container to the support, a container for auxiliary sole-portions, means for transferring an auxiliary portion from the container to the sole upon the support, and means for shifting the auxiliary portion to correspond to a right or left sole.

62. In a composite-sole-assembling machine, a support, a sole-container, means for transferring a sole from the container to the support, a container for auxiliary sole-portions, means for transferring an auxiliary portion from the container to the sole upon the support, and means for shifting the auxiliary portion during its transfer to correspond to a right or left sole.
63. In a composite-sole-assembling machine, a support, a sole-container, means for transferring a sole from the container to the support, a cement-receptacle, mechanism for delivering cement from the receptacle to the sole upon the support, means arranged to vary the application of cement according to whether a right or left sole is operated on, a shank-piece-container, means for transferring a shank-piece from its container to the cemented area of the sole, and means for shifting the shank-piece to correspond to the manner in which the cement is applied to the sole.
64. In an assembling machine, a support, means for delivering an article upon the support, means for exerting pressure upon the delivered article, means for applying to the supported article a second article, and means for bringing a third article into contact with the first and second articles.
65. In an assembling machine, a support, means for delivering an article upon the support, a clamping member for the delivered article, means for actuating the clamping member to secure the article to the support, means for applying to the secured article a second article, and means for bringing a third article into contact with the first and second articles.
66. In an assembling machine, a support, means for delivering an article to the support, means for applying a coating of adhesive to the article upon the support, means for applying another article to the coated surface, and means for applying still another article in contact with the last-mentioned article and with the surface first coated.
67. In an assembling machine, a plurality of supports, means for moving the supports to successive operating positions, means at one operating position for applying an article directly to the supports, means at a second position for applying a coating of adhesive to the supported article, means at a third position for placing an article upon the coated surface, and means at a fourth position for bringing still another article into co-operation with those already upon the support.
68. In an assembling machine, a support, means for delivering an article upon the support, means for applying to the supported article a second article, means for bringing a third article into contact with the first and second articles, and means for heating one of the articles.
69. In an assembling machine, a plurality of supports, means for moving the supports to successive operating positions, means at one operating position for applying articles directly to the supports, means at another operating position for placing articles upon those on the supports, means at still another position for bringing articles into co-operation with those already on the supports, and means at one of the operating positions for heating the articles applied thereto.
70. In an assembling machine, a support, means for delivering an article to the support, means for applying a coating of adhesive to the article upon the support, means for applying another article to the coated surface, means for heating said article, and means for applying still another article over the last-mentioned article and the coated surface.
71. In a composite-sole-assembling machine, a support, a sole-container, mechanism for transferring a sole from the container to the support with its tread-surface in contact therewith, mechanism for applying a retaining means to the upper surface of the supported sole, a filter-piece-container, and mechanism for transferring a filter-piece from its container into contact with the retaining means, this last-mentioned transferring means being arranged to apply a filter piece over an area spaced inwardly from the entire periphery of the sole.
72. In a composite-sole-assembling machine, a support, a shank-piece-container, mechanism for transferring a shank-piece from its container to a sole upon the support, a filler-piece-container, and mechanism for transferring a filler-piece from its container to the sole over the shank-piece.
73. In a composite-sole-assembling machine, a support, a sole-container, mechanism for transferring a sole from the container to the support, a shank-piece-container, mechanism for transferring a shank-piece from its container to the supported sole, a filler-piece-container, and mechanism for transferring a filler-piece from its container to the sole over the shank-piece.
74. In a composite-sole-assembling machine, a support, a sole-container, mechanism for transferring a sole from the container to the support, a shank-piece-container, mechanism for transferring a shank-piece from its container to the supported sole, a device for heating the shank-piece, a filler-piece-container, and mechanism for transferring a filler-piece from its container to the sole over the shank-piece.
75. In a composite-sole-assembling machine, a support, a sole-container, mechanism for transferring a sole from the container to

the support, a cement-receptacle, mechanism for delivering cement from the receptacle to the supported sole, a shank-piece-container, mechanism for transferring a shank-piece 5 from its container to the cemented area, a filler-piece-container, and mechanism for transferring a filler-piece from its container to the sole.

76. In a composite-sole-assembling machine, a support, a sole-container, mechanism for transferring a sole from the container to the support, a cement-receptacle, mechanism for delivering cement from the receptacle to the supported sole, a shank-piece-container, 10 mechanism for transferring a shank-piece from its container to the cemented area, a device for heating the shank-piece, a filler-piece-container, and mechanism for transferring a filler-piece from its container to the sole 15 over the shank-piece.

77. In a composite-sole-assembling machine, a rotatable turret, a plurality of supports fixed against movement about the periphery of the turret, means for intermittently rotating the turret to cause each support to occupy successive positions, a sole-container at one position, transferring mechanism arranged to travel between the sole container and supports, a filler-piece-container 25 at another position, and transferring mechanism arranged to travel between the filler-piece-container and supported soles.

78. In a composite-sole-assembling machine, a rotatable turret, a plurality of supports mounted upon the turret, means for intermittently rotating the turret to cause each support to occupy successive positions, a sole-container at one position, mechanism for transferring soles from the container to the supports, a cement-receptacle at a second position, means for delivering cement from the receptacle to the supported soles, a shank-piece-container at a third position, mechanism for transferring shank-pieces from their container to the cemented areas of the soles, a filler-piece container at a fourth position, and mechanism for transferring filler-pieces from their container to the soles. 40

79. In an assembling machine, a support, means for delivering an article to the support, means co-operating with the support to secure said article thereon, means for applying another article face to face with that upon the support, and means contacting with the outer faces for pressing the articles together. 50

80. In an assembling machine, a plurality of supports, means for moving the supports to successive operating positions, means for delivering articles to the supports at such successive positions, one of said articles being applied directly to the support and another into co-operation with such article, a member movable into contact with the article resting 60 on the support to secure it thereon, and means

at one of the positions for applying pressure over substantially the entire area covered by the assembled articles.

81. In an assembling machine, a plurality of supports, means for moving the supports to successive operating positions, means for delivering articles to the supports at such successive positions, one of said articles being applied directly to the support and another into co-operation with such article, and means at the position at which the last article is applied for first removing articles from the delivering means and then pressing them together with the previously delivered articles. 70

82. In an assembling machine, a plurality of supports, independent means situated at different operating positions for holding stacks of articles, means for producing relative movement between the supports and holding means to bring about co-operation between the different holding means and supports, means for simultaneously transferring articles from the stacks in the holding means to the supports, and means mounted independently of the transferring means at one 80 of the stack-holders for applying pressure to the articles upon the supports after their removal from the stacks.

83. In an assembling machine, a plurality of supports, independent article-holding means situated at different operating positions, means for producing relative movement between the supports and holding means to bring about co-operation between the different holding means and supports, means for simultaneously transferring articles from the holding means to the supports, means associated with one of the holding means for advancing articles therefrom toward the support at that position, and means associated 90 with said advancing means for first removing articles therefrom and then applying pressure to the articles upon the support. 95

84. In an assembling machine, a support, means for delivering an article to the support, means movable over the supported article and out of contact therewith for applying a coating of adhesive thereto during the travel of such applying means, means for applying another article to the coated surface, 100 and means for pressing the articles together. 110

85. In an assembling machine, a support, means for delivering an article to the support, means for securing the delivered article upon the support, means for applying a coating of adhesive to the secured article, means for applying another article to the coated surface, and means for pressing the last-mentioned article toward that secured to the support. 120

86. In an assembling machine, a support, means for engaging pieces of material and bringing them together upon the support, means for heating certain of the thus-engaged pieces, and means for applying pressure and 125 130

heat to the pieces while they are at rest upon the support.

87. In an assembling machine, an article-support, a container for a plurality of articles, means for heating articles in the container, means for transferring one by one articles from the container in which they are heated directly to articles carried by the support, and means for applying pressure to the transferred articles.

88. In an assembling machine, a plurality of supports, means for moving the supports to successive operating positions, means for delivering articles to the supports at such successive positions, means at one of the positions for heating the articles thereat, and means at another position for pressing the articles together.

89. In an assembling machine, a support, means for delivering an article to the support, means for applying a coating of adhesive to the article upon the support, means for applying another article to the coated surface while on such support, means for heating the last-mentioned article, and means for applying pressure to the articles.

90. In an assembling machine, a support, means for delivering an article upon the support, means for applying to the supported article a second article, means for bringing a third article into contact with the first and second articles, and means for pressing all the articles together.

91. In an assembling machine, a plurality of supports, means for moving the supports to successive operating positions, means at one operating position for applying articles directly to the supports, means at another operating position for placing articles upon those on the supports, transferring means at still another position for bringing articles into co-operation with those already on the supports, and means at the last-mentioned position for removing the articles from the transferring means and then pressing together all the articles upon each support.

92. In an assembling machine, a support, means for delivering an article upon the support, means for applying to the supported article a second article, means for bringing a third article into contact with the first and second articles, means for heating one of the articles, and means contacting with the assembled articles for applying pressure thereto.

93. In a composite-sole-assembling machine, a support having a surface curved to generally correspond to the contour of a shoe-bottom, a sole-container, means for transferring a sole from the container to the curved surface of the support, a container for auxiliary sole-portions, means for transferring said auxiliary portions from the container to the sole upon the support, and a pressure member movable into contact with the aux-

iliary portion upon the sole over substantially the entire area covered thereby.

94. In a composite-sole-assembling machine, a support having a surface curved to generally correspond to the contour of a shoe-bottom, means for causing the travel of the support to different positions, a sole-container at one position, mechanism at said position for transferring the sole from the container to the curved surface of the support, a container at a succeeding position for auxiliary sole-portions, mechanism at this position for transferring an auxiliary portion from its container to the supported sole, and mechanism at one of the positions for pressing the auxiliary portion toward the sole.

95. In a composite-sole-assembling machine, a rotatable turret, a plurality of supports mounted upon the turret, means for intermittently rotating the turret to cause each support to occupy successive positions, mechanism at one position for applying a sole to each support, mechanism at another position for engaging and retaining an auxiliary portion, and means for moving the retaining mechanism to apply the retained portion to the supported sole and to exert pressure upon the associated sole-elements.

96. In a composite-sole-assembling machine, a support, a sole-container, means for transferring a sole from the container to the support, a shank-piece-container, means for transferring a shank-piece from said container to the supported sole, and a pressure device arranged to force the shank-piece against the sole.

97. In a composite-sole-assembling machine, a support, a sole-container, mechanism for transferring a sole from the container to the support, a shank-piece-container, mechanism for transferring a shank-piece from its container to the supported sole, a device for heating the shank-piece, a filler-piece-container, mechanism for transferring a filler-piece from its container to the sole over the shank-piece, and mechanism for forcing the filler-piece against the heated shank-piece and the shank-piece against the sole.

98. In a composite-sole-assembling machine, a rotatable turret, a plurality of supports mounted upon the turret, means for intermittently rotating the turret to cause each support to occupy successive positions, mechanism movable radially of the turret at one position for applying a sole to each support, mechanism movable radially of the turret at another position for applying an auxiliary portion to the thus supported sole, and mechanism at one of the positions for applying pressure to the assembled sole-elements.

99. In a composite-sole-assembling machine, a rotatable turret, a plurality of supports mounted upon the turret, means for intermittently rotating the turret to cause each support to occupy successive positions, a sole-

5 container at one position, mechanism for transferring soles from the container to the supports, a cement-receptacle at a second position, means for delivering cement from the receptacle to the supported soles, a shank-piece-container at a third position, mechanism for transferring shank-pieces from their container to the cemented areas of the soles, a 10 filler-piece-container at a fourth position, and mechanism for transferring filler-pieces from their container to the soles and acting to force all the portions of the composite sole together.

100. In a machine of the class described, a 15 work-support, means for coating a surface of the supported work, means for applying an element to the coated surface, and means acting upon the surface between its coating and the application of the element to maintain it 20 in condition for such application.

101. In an assembling machine, a work-support, means for moving the support to different operating positions, means at one position for coating a surface of the supported work, means at another position for applying an article to the coated surface, and means situated at an intermediate position and arranged to maintain the coating in condition to receive the applied article.

102. In an assembling machine, a work-support, means for moving the support to different operating positions, means at one position for applying an adhesive to the supported work, means at another position for heating the coating of adhesive, and means at still another position for applying an article to the heated surface.

103. In an assembling machine, a work-support, means for moving the support to different operating positions, means at one position for applying an adhesive to the supported work, means at another position for heating the coating of adhesive and applying an article thereto, and means at still another position for applying an article to the heated surface.

104. In an assembling machine, a work-support, means for moving the support to different operating positions, means at one position for applying an adhesive to the supported work, means at another position for heating the coating of adhesive, and means at a succeeding position for heating an article and applying it to the coated surface.

105. In an assembling machine, a work-support, means for moving the support to different operating positions, means at one position for applying an adhesive to the supported work, means at another position for heating the coating of adhesive, means at a succeeding position for heating an article and applying it to the coated surface, and means at still another position for applying an article over the coated surface and the previously applied article.

106. In a sole-assembling machine, a sole-support, mechanism for delivering cement to a supported sole, a heating device acting upon the cemented surface, and mechanism for applying an auxiliary sole-element to the heated surface.

107. In a sole-assembling machine, a sole-support, mechanism for delivering cement to a supported sole, a heating device acting upon the cemented surface, and mechanism arranged to apply a filler-piece to the heated surface.

108. In a sole-assembling machine, a sole-support, mechanism for delivering cement to a supported sole, a heating device acting upon the cemented surface, mechanism for applying a shank-piece to the heated surface, and mechanism for applying a filler-piece over the heated surface and the shank-piece.

109. In a composite-sole-assembling machine, a support, means for causing the travel of the support to different positions, a sole-container at one position, mechanism for transferring a sole from the container to the support, a cement-receptacle at another position, mechanism for delivering cement from the receptacle to the sole upon the support, a heating device acting upon the cemented surface at a succeeding position, a container for filler-pieces at still another position, and means for transferring a filler-piece from its container to the heated surface of the sole.

110. In a composite-sole-assembling machine, a support, means for causing the travel of the support to different positions, a sole-container at one position, mechanism for transferring a sole from the container to the support, a cement-receptacle at another position, mechanism for delivering cement from the receptacle to the sole upon the support, a heating device acting upon the cemented surface at a succeeding position, a container for shank-pieces at said position, mechanism for transferring a shank-piece from its container to the cemented surface, a container for filler-pieces at still another position, and means for transferring a filler-piece from its container and applying it over the heated cement and the shank-piece.

111. In a composite-sole-assembling machine, a support, means for causing the travel of the support to different positions, a sole-container at one position, mechanism for transferring a sole from the container to the support, a cement-receptacle at another position, mechanism for delivering cement from the receptacle to the sole upon the support, a heating device acting upon the cemented surface at a succeeding position, a container for shank-pieces at said position, means for heating the shank-pieces in their container, mechanism for transferring a heated shank-piece from its container to the cemented surface, a container for filler-pieces at still another position, and means for transferring

a filler-piece from its container and applying it over the heated cement and the shank-piece.

112. In a machine of the class described, a traveling support, means for placing an article upon the support in a predetermined position, a container, means for moving the support from its article-receiving relation into cooperation with the container, means for feeding an article from the container and temporarily holding it in a definite relation to an article upon the support, and a movable member arranged to engage the article thus held and convey it into contact with the article upon the support while maintaining the established relation between the articles. 70

113. In a machine of the class described, a traveling support, means for placing an article upon the support in a predetermined position, a container, means for moving the support from its article-receiving relation into cooperation with the container, means for feeding an article from the container and temporarily holding it in a definite relation to an article upon the support, a movable member arranged to engage the article thus held and convey it into contact with the article upon the support while maintaining the established relation between the articles, and means for applying pressure to the member to force the articles together. 80

114. In a machine of the class described, a support, means for placing an article upon the support in a predetermined position, a container, means for feeding an article from the container and temporarily holding it in a definite relation above an article upon the support, a member arranged to descend into engagement with an article thus held and to maintain the established relation, and means for thereafter moving the member to lower the engaged article into contact with that upon the support. 90

115. In a composite-sole-assembling machine, a sole-support, a sole-container, mechanism for taking a sole from the container and placing it upon the support in a predetermined position, a container for auxiliary sole-portions, mechanism for feeding a sole-portion from the container and temporarily holding it in a definite relation to the position it is to occupy upon the sole, a movable member having a projection arranged to enter a portion thus held, and means for moving the member to convey the auxiliary portion to the sole and apply it in the desired relation. 95

116. In a composite-sole-assembling machine, a sole-support, a sole-container, mechanism for taking a sole from the container and placing it upon the support in a predetermined position, a container for auxiliary sole-portions, mechanism for feeding a sole-portion from the container and temporarily holding it in a definite relation to the position it is to occupy upon the sole, a movable member

having a projection arranged to enter a portion thus held, means for moving the member to convey the auxiliary portion to the sole and apply it in the desired relation, and power-actuated means for pressing the conveying member toward the support. 105

117. In a machine of the class described, the combination with a work-support, of a work-locating member movable upon the support, means arranged to determine the position of the locating member in accordance with the size of the work to be supported and temporarily fix said member against movement, and means for thereafter releasing the member for the succeeding setting. 115

118. In a machine of the class described, the combination with a work-support, of a work-locating member movable upon the support, and means acting in the operation of the machine and independently of the work for adjusting the work-locating member to correspond to the size of the work. 125

119. In a machine of the class described, a device having a work-supporting surface, a locating projection movable in proximity to the supporting surface and arranged for contact with the work thereon, and automatic means arranged to move the projection in advance of the application of work to the support and in a direction substantially parallel to the supporting surface to correspond to the size of said work to be operated upon. 135

120. In a machine of the class described, the combination with a work-support, of a work-locating member movable upon the support, means arranged to determine the position of the locating member in accordance with the size of the work to be supported, and automatic means arranged to secure the locating member temporarily in the position thus determined. 145

121. In a machine of the class described, the combination with a work-support, of a work-locating member movable upon the support, means arranged to determine the position of the locating member in accordance with the size of the work to be supported, means arranged to secure the locating member temporarily in the position thus determined, and means for releasing the securing means. 155

122. In a machine of the class described, the combination with a work-support, of a work-locating member movable upon the support, means arranged to determine the position of the locating member in accordance with the size of the work to be supported, means arranged to secure the locating member temporarily in the position thus determined, and means acting in the operation of the machine for releasing the securing means. 165

123. In a machine of the class described, the combination with a work-support, of a work-locating member movable upon the support, means acting in the operation of the machine

- for adjusting the work-locating member, means arranged to secure the locating member temporarily in the position thus determined, and means acting in the operation of the machine for releasing the securing means. 5 members being mounted upon the carrier, and 65 means arranged to adjust the position of the carrier to vary the normal relation of the engaging means to the work.
124. In a machine of the class described, a work-support having an opening, a slide movable adjacent to the support and having a projection extending through the opening, a spring exerting its force to move the slide, and automatically operating means for locking the slide against the force of the spring. 10 70
125. In a machine of the class described, a traveling work-support having an opening, a slide movable adjacent to the support and having a projection extending through the opening, a spring exerting its force to move the slide, and means for locking the slide against the force of the spring, and means contacting with the lock during travel of the support to release the slide. 15 75
126. In a sole-assembling machine, a sole-support, a member co-operating with the sole to locate it upon the support, and means acting in the operation of the machine prior to the application of a sole to the support to move the locating member in accordance with the length of the sole to be supported. 20 80
127. In a sole-assembling machine, a sole-support, means for operating upon the supported sole, a member co-operating with the sole to locate it upon the support, means for moving the locating member, means for temporarily securing the locating member in the position to which it is moved, and means acting upon the completion of an operation of the machine for releasing the securing means. 25 85
128. In a machine of the class described, a work-support, means for operating upon the supported work, means movable toward and from the support for engaging the work to force it against said support and secure it for the operation, and means controlled by contact with the work to initiate each actuation of the engaging means. 30 90
129. In a machine of the class described, a work-support, means movable toward the support for engaging the work to secure it, means arranged to vary the normal relation of the engaging means toward and from the support, and means controlled by contact with the work to actuate the engaging means. 35 95
130. In a machine of the class described, a work-support, a carrier movable toward and from the support, a work-securing member, and a member for contact with the work and arranged to govern the securing member, said members being mounted upon the carrier. 40 100
131. In a machine of the class described, a work-support, a carrier movable toward and from the support, a work-securing member, a member for contact with the work and arranged to actuate the securing member, said 45 105
- members being mounted upon the carrier, and 110 means arranged to adjust the position of the carrier to vary the normal relation of the engaging means to the work. 115
132. In a machine of the class described, a work-support, a carrier movable toward and from the support, a work-securing lever fulcrumed upon the carrier, a slide movable upon the carrier and arranged to contact with the work, and connections between the lever and slide. 120
133. In a machine of the class described, a work-support, a carrier movable toward and from the support, a work-securing lever fulcrumed upon the carrier, a slide movable upon the carrier and arranged to contact with the work, connections between the lever and slide, and means for normally moving the lever from the support and the slide toward said support. 125
134. In a machine of the class described, a work-support, a carrier movable toward and from the support, a work-securing lever fulcrumed upon the carrier, a slide movable upon the carrier and arranged to contact with the work, a spring inserted between the carrier and slide and being yieldable upon contact between the slide and work, connections between the lever and slide, and a spring acting to draw the carrier toward the support. 130
135. In a machine of the class described, a work-support, means for engaging the work to secure it upon the support, means controlled by contact with the work for governing the engaging means, means for producing such contact, and means for governing the action of the contact-producing means. 135 100
136. In a machine of the class described, a work-support, means for engaging the work to secure it upon the support, means controlled by contact with the work for governing the engaging means, means for producing such contact, and means controlled by contact of the work for governing the action of the contact-producing means. 140 105
137. In a machine of the class described, a work-support, a carrier movable toward and from the support, a work-securing member movable upon the carrier, means for temporarily holding the carrier with the engaging member out of contact with the work, and means operated by contact with the work for releasing the carrier, the securing member being thereafter moved on the carrier. 145 110
138. In a machine of the class described, a work-support, a carrier movable toward and from the support, a work-securing lever fulcrumed upon the carrier, a slide movable upon the carrier and arranged to contact with the work, connections between the lever and slide, means for moving the carrier to produce contact of the slide, means for locking the carrier against movement, and a 150 115

member arranged to be moved by contact of the work when it is applied to the support and to thereby release the locking means.

139. In a machine of the class described, the combination with a work-support, of a work-locating member movable upon the support in advance of the application of the work for engagement with one end of said work, and means contacting with the opposite extremity of the located work and with the face thereof opposite the support to force it against said support.

140. In a machine of the class described, the combination with a work-support, of a work-locating member movable upon the support, means arranged to determine the position of the locating member in accordance with the size of the work to be supported, and means movable into contact with the located work and arranged for actuation by such contact to secure the work to the support.

141. In a sole-assembling machine, a sole-support, a member for engaging the sole to clamp it upon the support, and means movable into contact with the end of the supported sole and arranged to actuate the clamping means upon such contact.

142. In a sole-assembling machine, a sole-support, a member for engaging the sole to clamp it upon the support, means movable into contact with the end of the supported sole and arranged to actuate the clamping means upon such contact, a lock for temporarily retaining the actuating means against movement, and a movable member arranged for contact with a sole applied to the support and acting upon the lock to release the actuating means.

143. In a sole-assembling machine, a sole-support, a locating member associated with the support for co-operation with one extremity of the sole, and means movable into contact with the edge and upper face of the opposite extremity of the sole for clamping it upon the support while it is under the influence of the locating member.

144. In a sole-assembling machine, a sole-support, a locating member associated with the support for co-operation with one extremity of the sole, and sole-clamping means and actuating means therefor movable toward and from the support, the actuating means being arranged to cause the clamping of the supported sole upon contact with the end opposite the locating member.

145. In a sole-assembling machine, a sole-support, a locating member associated with the support for co-operation with one extremity of the sole, means movable into contact with the opposite extremity of the sole for clamping it upon the support, and means arranged for contact with the sole at an intermediate point and movable thereby to control the clamping means.

146. In a machine of the class described, a work-support, means for moving the support, a movable work-engaging member mounted upon the support, a spring for moving the engaging member, means acting in the travel of the support and prior to the application of work thereto for changing the condition of the spring, and means acting in the continued travel of the support for exercising a further control over the spring.

147. In a machine of the class described, a work-support, means for moving the support through a plurality of operating positions, operating mechanism at each position into co-operation with which the support is moved, a movable work-engaging member associated with the support, a spring for moving the engaging member, means situated at one of the operating positions for tensioning the spring, and means situated at another operating position for releasing the spring.

148. In a machine of the class described, a work-support, means for moving the support through a plurality of operating positions, operating mechanism at each position into co-operation with which the support is moved, a securing member for the work movable with the support, a spring for moving the securing member, means situated at an operating position and arranged to cause the spring to act, and means associated with a succeeding operating position and arranged to cause the securing member to release the work and the spring to be tensioned.

149. In a machine of the class described, a work-support, means for moving the support through a plurality of operating positions, securing means for the work movable with the support, means situated at an operating position and arranged to apply work to the support, a device for contact with the applied work arranged to control the engagement of the securing means with the work, and means associated with a succeeding operating position and arranged to cause the securing means to release the work.

150. In a machine of the class described, a work-support, means for moving the support, a movable work-locating member associated with the support, means effective in the movement of the support for setting the locating member, and means effective in the movement of the support for destroying said setting.

151. In a machine of the class described, a work-support, means for moving the support through a plurality of operating positions, a movable work-locating member associated with the support, means situated at one of the operating positions for setting the locating member, and means arranged to vary the relation of the setting means to the locating member.

152. In a machine of the class described, a work-support, means for moving the support through a plurality of operating positions, a

movable work-locating member associated with the support, setting means co-operating with the locating member between the last and first operating positions, and previously acting means for releasing such locating member.

153. In a machine of the class described, a work-support, means for moving the support through a plurality of operating positions, a movable work-engaging member associated with the support, means acting in the travel of the support for moving the engaging member, means for temporarily locking the engaging member in the position to which it is moved, and means acting in the travel of the support for releasing the locking means.

154. In a machine of the class described, a work-support, means for moving the support through a plurality of operating positions, a movable work-engaging member associated with the support, means acting in the travel of the support for moving the engaging member, means for temporarily locking the engaging member in the position to which it is moved, means carried by the support for moving the engaging member in the opposite direction, and means acting in the travel of the support for releasing the locking means to permit the last-mentioned moving means to act.

155. In a machine of the class described, a work-support, means for moving the support through a plurality of operating positions, a movable work-locating member associated with the support, means associated with one of the operating positions for setting the locating member, means carried by the support for locking the locating member in its set position, a spring acting upon the locating member, and means for releasing the locating member to permit the spring to act.

156. In a machine of the class described, a work-support, mechanism for operating upon the supported work, a member arranged to be set by contact with the work during the application of said work to the support, and means for moving the set member to control the operating mechanism.

157. In a machine of the class described, a traveling work-support, mechanism for operating upon the supported work, and means movable upon the support by the work and acting in the travel of said support to control the operating mechanism.

158. In a machine of the class described, a work-support, mechanism for operating upon the supported work, means movable upon the support for controlling the operating mechanism, means for temporarily retaining the controlling means in the position to which it is moved, and means for restoring the controlling means to its normal position.

159. In a machine of the class described, a work-support, mechanism for operating upon

the supported work, a member arranged to be moved by contact with work applied to the support to a position to control the operating mechanism, means for thereafter moving the member to effect such control, and means for moving the controlling member from such position.

160. In a machine of the class described, a traveling work-support, mechanism for operating upon the supported work, a member upon the support acting in the travel thereof to control the operating mechanism, said member being movable to a position ineffective to control such operating mechanism, and means for effecting such movement.

161. In a machine of the class described, a traveling work-support, a plurality of mechanisms for operating upon the supported work, and a member arranged to be moved by contact with the work applied to the support to a position for controlling an operating mechanism, said member being movable to a position to control another operating mechanism.

162. In a machine of the class described, a work-support provided with an opening in its work-supporting surface, a member movable through the opening into the space to be occupied by the supported work, mechanism for operating upon the supported work, and connections to the member for controlling the operating mechanism.

163. In a machine of the class described, a work-support provided with an opening, a member movable through the opening into the space to be occupied by the supported work, means for moving the member toward said space, frictional means for retaining the member in the position to which it is moved, mechanism for operating upon the supported work, and connections to the member for controlling the operating mechanism.

164. In a machine of the class described, a work-support, means for engaging the work to secure it upon the support, means for operating upon the secured work, and means controlled by contact with the work for governing the engaging means and the operating means.

165. In a machine of the class described, a support, means for moving the support through a plurality of operating positions, means for applying an article to the support in one position, means for operating upon the article in another position, and means movable with the support and arranged to control the operating means at said other position only when the article has been applied to the support.

166. In a machine of the class described, a support, means for moving the support through a plurality of operating positions, means for applying an article to the support in one position, means for operating upon the article in another position, and means acting

during the movement of the support and arranged to start the operating means at said other position only when the article has been applied to the support.

5 167. In a machine of the class described, a support, means for moving the support through a plurality of operating positions, means for applying an article to the support in one position, means for operating upon the 10 article in another position, and means arranged normally to start operation of the applying means as a result of the movement of the support and to start the associated operating means only after the application of 15 an article to the support.

168. In a machine of the class described, a work-support, means for moving the support through a plurality of positions, operating mechanisms situated at said positions and a 20 device associated with the support and movable by the work, said device being arranged to control the operating mechanisms.

169. In a machine of the class described, a work-support, means for moving the support through a plurality of positions, operating mechanisms situated at said positions, a contact member associated with the support for movement by the work, and means movable by 25 the contact member and arranged to control the operating mechanisms.

170. In a machine of the class described, a work-support, means for moving the support through a plurality of positions, operating mechanisms situated at said positions, and a device associated with the support and movable by the work, said device being arranged to control the operating mechanism at one 35 position prior to its movement by the work and at another position after its movement thereby.

171. In a machine of the class described, a work-support, means for moving the support through a plurality of positions, operating mechanisms situated at said positions, and a device associated with the support and movable by the work, said device being arranged to control the operating mechanism at the first 45 position prior to its movement by the work and at the succeeding positions after its movement thereby.

172. In a machine of the class described, a work-support, means for moving the support through a plurality of positions, operating mechanisms at the positions, securing means 55 for the work movable with the support, means situated at an operating position and arranged to apply work to the support, a device for contact with the applied work arranged to control the engagement of the securing means with the work and to control the operating mechanisms, and means associated with a succeeding operating position and arranged to cause the securing means 60 to release the work.

173. In a sole-assembling machine, a sole-support, means for moving the support through a plurality of positions at which operations are performed upon the supported sole, a member movable into engagement with the sole to clamp it to the support, means exerting a constant actuating tendency upon the member, and means situated at different operating positions and respectively opposing the actuating means and releasing it for action. 75

174. In a sole-assembling machine, a sole-support, means for moving the support through a plurality of positions at which operations are performed upon the supported sole, a member movable into engagement with the sole to clamp it to the support, a device carried by the support and arranged for actuation by a sole applied at one operating position to control the engagement of the clamping means, and means associated with another operating position for releasing the clamping means. 80

175. In a sole-assembling machine, a sole-support, means for moving the support through a plurality of positions at which operations are performed upon the supported sole, a member movable into engagement with the sole to clamp it to the support, a sole-container at an operating position, means for transferring a sole from the container to the support, a device carried by the support and actuated by the transferred sole to control the engagement of the clamping means, and means associated with a succeeding operating position for releasing the clamping means. 95

176. In a sole-assembling machine, a sole-support, means for moving the support through a plurality of positions at which operations are performed upon the supported sole, a sole-locating projection movable upon the support to provide for its engagement with soles of different lengths, means acting between operating positions for setting the locating projection, means for temporarily locking the projection as thus set, and means acting prior to the setting means for unlocking the locating projection. 105

177. In a sole-assembling machine, a sole-support, means for moving the support through a plurality of positions at which operations are performed upon the supported sole, a sole-locating projection movable upon the support to provide for its engagement with soles of different lengths, a contact member associated with an operating position for co-operation with the locating member to set it, means arranged to vary the position of the contact member toward and from the path of the projection, means for temporarily locking the projection as thus set, and means acting prior to the setting means for unlocking the locating projection. 115 120 125

178. In a sole-assembling machine, a sole-support, means for moving the support through a plurality of positions at which operations are performed upon the supported sole, means at an operating position for delivering a sole to the support, means at a succeeding operating position for removing said sole from the support, a sole-locating projection movable upon the support to provide for its engagement with soles of different sizes, means acting before the support reaches the delivering position for setting the locating projection, means for temporarily locking the projection thus set, and means acting after the support leaves the removing position for releasing the locking means. 70
179. In a sole-assembling machine, a sole-support, means for moving the support through a plurality of positions, mechanism for applying a sole to the support at the first position, mechanism for making applications to said sole at other positions, and means arranged to start the operation of said other applying mechanisms only when the support has received a sole in the first position. 80
180. In a sole-assembling machine, a sole-support, means for moving the support through a plurality of positions, mechanism for applying a sole to the support at the first position, mechanism for making applications to said sole at other positions, and means arranged normally to start the operation of the sole-applying mechanism and to start the operation of other applying mechanisms only when the sole has been applied to the support. 90
181. In a sole-assembling machine, a sole-support, means for moving the support through a plurality of positions, mechanisms at said positions for operating upon the work, a member movable upon the support for contact with the applied sole, and a member movable by the contact member and arranged to control in its different positions different operating mechanisms. 95
182. In a sole-assembling machine, a sole-support, means for moving the support through a plurality of positions at which operations are performed upon the supported sole, mechanism at the first operating position for applying a sole to the support, mechanisms at other positions for operating upon the applied sole, a member associated with the support and being movable by contact with the applied sole, and a member connected with this contact member to be moved thereby from an initial position at which it is arranged to control the mechanism in the applying position to one in which it is arranged to control the associated operating mechanisms. 110
183. In a machine for operating upon pairs of soles, a sole-support having surfaces curved to correspond respectively to the sur- 115
- face contour of a right and a left shoe bottom, a mounting for the support arranged to permit it to be shifted, and operating mechanism having surfaces curved similarly to those of the support and co-operating therewith. 120
184. In a machine of the class described, an article-support, means for operating upon articles on the support, means arranged to hold articles, arms pivoted between the support and holding means, a carrier-bar pivoted upon the arms, an article-engaging device including an element movable at the lower extremity of the bar, and means for oscillating the arms to move the engaging device between the holding means and support. 125
185. In a machine of the class described, an article-support, means for operating upon articles on the support, means arranged to hold articles, arms pivoted between the support and holding means, a carrier-bar pivoted upon the arms, an article-engaging device including an element movable at the lower extremity of the bar, and means for oscillating the arms to move the engaging device from a normal position above the holding means down into contact with an article, upwardly from the holding means with the engaged article, and downwardly to the support to deliver the article thereto. 130
186. In a machine of the class described, an article-support, means for operating upon articles on the support, means arranged to hold articles, arms pivoted between the support and holding means, a carrier-bar pivoted upon the arms, an article-engaging device carried by the lower extremity of the bar, a gear arranged to turn with each arm, a rack-bar meshing with the gears, and means for reciprocating the rack-bar. 135
187. In a machine of the class described, a revoluble support, mechanisms including means for operating upon articles on said support and means for holding articles, and means movable along the radius from the axis of revolution and arranged to lift articles from the holding means and deposit them upon the upper surface of the support, maintaining the same relation of the articles with respect to the horizontal throughout their travel. 140
188. In a machine of the class described, a revoluble support, mechanisms for operating upon articles on said support, means situated at a plurality of operating positions for holding articles, and transferring devices movable along radii from the axis of revolution and arranged to successively lift articles from the holding means and deposit them in a vertical series upon one another on the support. 145
189. In a sole-assembling machine, a sole-support, means for operating upon the supported sole, a container arranged to hold a stack of soles, a table adjacent to the container, means for feeding the soles one by one 150

from the container to the table, and vertically oscillatory means for successively transferring the soles from the table to the support.

190. In a sole-assembling machine, a sole-support, means for operating upon the supported sole, a container arranged to hold a stack of soles, a table adjacent to the container, means for feeding the soles one by one from the container to the table, and a sole-engaging device arranged to oscillate in a vertical plane between the table and support and to maintain the sole in a horizontal relation during its transfer.

191. In a sole-assembling machine, a sole-support, associated means for operating upon a supported sole, sole-holding means, a device having projections to engage a sole and being maintained normally above the holding means, and means arranged to first move the device to cause its projections to enter the sole carried by the holding means and then to move said device first upwardly and then downwardly over the support to transfer the sole thereto.

192. In a composite-sole-assembling machine, a rotatable turret, a plurality of supports mounted upon the turret, means for securing a sole upon each support, means for intermittently rotating the turret to cause each support to occupy successive positions, containers for sole-elements at a plurality of positions, transferring devices for the sole-elements arranged to move back and forth between the containers and support, and mechanism for simultaneously effecting such movements.

193. In a machine of the class described, a support having article-locating means, an article-transferring device co-operating with the support and having an article-penetrating projection, and a pressure member movable into registration with the locating means and being arranged to travel with said projection and to move independently thereof.

194. In a machine of the class described, a support having article-locating means, and a device for delivering articles to the support, said device having article-engaging portions and a pressure member for contact with the article adjacent to the locating means at the time of delivery and arranged to force said article into co-operation with the locating means.

195. In a machine of the class described, a support having a projection arranged to enter an opening in an article, a device for delivering articles to the support, said device having an article-penetrating projection, and a pressure member for contact with the article at opposite sides of its opening.

196. In a machine of the class described, article-holding means, an article-support, a carrier-bar arranged to oscillate between the holding means and support, a transfer device having article-engaging portions mounted

upon the bar, an arm extending from the bar and being independent of the mounting of the transfer device, and a yieldable member mounted upon the arm for contact with the article.

197. In a machine of the class described, an article-support, a member movable upon the support and being arranged for contact with an article delivered thereto, mechanism controlled by the movement of said member, and an article-engaging device movable to deliver articles to the support and being substantially aligned at the time of delivery with the movable member.

198. In a sole-assembling machine, a transferring device having a projection arranged to penetrate the surface of a sole near its center, and a pressure member mounted with the projection for contact with the sole near one extremity only.

199. In a sole-assembling machine, a transferring device having a projection arranged to penetrate the surface of a sole near its center, and a pressure member mounted with the projection for contact with the sole near one extremity and being yieldable and arranged to maintain contact with the sole after the withdrawal of the projection.

200. In a sole-assembling machine, a sole-support having a projection co-operating with the sole to locate it, and a device for delivering to the support, said device having portions arranged to engage a sole near its center, and a pressure member arranged for contact with the sole adjacent to the support-projection at the time of delivery.

201. In a machine of the class described, a container arranged to hold a stack of objects and having opposite side walls mounted for movement toward and from each other in co-operation with all the objects of the stack, and means arranged to move said walls simultaneously through different distances bearing to each other a predetermined relation.

202. In a machine of the class described, an article-container having opposite side walls mounted for movement toward and from each other, and means arranged to move said walls simultaneously through different distances, such movements bearing respectively definite relations to the dimensions of the articles.

203. In a machine of the class described, an article-container having opposite side walls mounted for movement toward and from each other, and a cam having surfaces of different contour acting to move the respective walls.

204. In a sole-assembling machine, a sole-container having opposite walls arranged to co-operate respectively with the heel and toe ends of the contained soles, means associated with one of the walls and arranged to support the corresponding sole-ends at a differ-

ent height from the opposite ends, and means arranged to move the walls simultaneously toward and from the transverse axes of the soles.

5 205. In a composite-sole-assembling machine, a sole-container having opposite walls arranged for co-operation with the heel and toe ends of the contained soles, said walls being movable toward and from each other, 10 and means arranged to move said walls through distances corresponding to the lengths of the heel and toe-portions of soles of different sizes.

15 206. In a machine of the class described, a container having side walls and a bottom wall arranged to support an article, an auxiliary support situated within the container at one side of the bottom wall and upon which the article rests, and means arranged to permit 20 the vertical relation between the wall and support to be varied.

25 207. In a machine of the class described, a container having an article-supporting bottom wall, an auxiliary support situated at one side of the bottom wall, means arranged to permit the height of the auxiliary support to be varied, and a gage member situated at one side of the container for contact with the articles therein, said gage member being 30 movable with the auxiliary support.

35 208. In a machine of the class described, a container having an article-supporting bottom wall, an auxiliary support situated at one side of the bottom wall, means arranged to permit the height of the auxiliary support to be varied, a gage member situated at one side of the container for contact with the articles therein and resting upon the auxiliary support, and means independent of the 40 auxiliary support for guiding the gage member to permit its movement with said support.

45 209. In a machine of the class described, an article-container having a side wall movable toward and from the opposite side of the container, an article-support situated adjacent to the movable container-wall and being vertically movable, and a gage member mounted for vertical movement upon the 50 movable side wall and resting upon the support.

55 210. In a machine for assembling composite molded soles, a sole-container having a bottom wall upon which the forepart of a sole may rest, a support within the container for the heel-portion of the sole, and means arranged to permit relative vertical movement between the bottom wall and support.

60 211. In a machine for assembling composite molded soles, a sole-container having a bottom wall upon which the forepart of a sole may rest, a support within the container for the heel-portion of the sole, means arranged to permit relative vertical movement 65 between the bottom wall and support, and a

gage for the heel-portion of the sole, said gage being guided to move upon the container and resting on the heel-support.

212. In a machine of the class described, a traveling support having a receiving surface 70 upon which articles are to be operated on, a container arranged to hold a stack of articles, an intermediate support past which the operating support travels, means for feeding articles from the bottom of the stack in the 75 container to the intermediate support, and transferring means arranged to move into engagement with articles upon the intermediate support and to elevate and deposit them upon the receiving surface. 80

213. In a machine of the class described, a support revoluble through a succession of operating positions, an article-container situated at one position, a table located at one side of the container and in a direction therefrom circumferentially of the path of the support, means for feeding an article from the 85 container to the table, and means independent of the table for transferring an article from the table to the support. 90

214. In a machine of the class described, an article-support, means for locating an article upon the support in a predetermined position, means for holding articles, means for transferring an article from the holding means to the support, means associated with the holding 95 means for adjusting the article to a position corresponding to that determined by the locating means, and means for actuating the adjusting means under the power of the machine. 100

215. In a machine of the class described, a support upon which articles are to be operated upon in a predetermined position, means for holding articles, means for transferring an article from the holding means to the support, and means associated with the holding 105 means for adjusting the article longitudinally and transversely to a position corresponding to that which it is to occupy upon the support. 110

216. In a machine of the class described, a support upon which articles are to be operated upon in a predetermined position, means for holding articles, means for transferring an article from the holding means to the support, and plural pressure devices associated with the holding means and being independent of the transferring means for adjusting the article to a position corresponding to that which it is to occupy upon the support, 120 the pressure exerted by one of the devices continuing after that of the other. 115

217. In a machine of the class described, a support upon which articles are to be operated upon in a predetermined position, means for holding articles, means for transferring an article from the holding means to the support, and automatic means movable longitudinally and transversely of the articles into contact therewith and releasing them prior 125 130

to their transfer to position them to correspond to the position they are to occupy upon the support.

218. In a machine of the class described, a support upon which articles are to be operated upon in a predetermined position, means for holding articles, means for transferring an article from the holding means to the support, and automatic means movable in directions at right angles to each other into contact with and then from the articles prior to their transfer to position them to correspond to the position they are to occupy upon the support.

219. In a sole-assembling machine, a sole-support, means for locating a sole upon the support in a predetermined position, a sole-holder associated with the support, sole-transferring means acting between the holder and support, and adjusting means arranged to locate the soles prior to their transfer in a definite relation to the position they are to occupy upon the support.

220. In a sole-assembling machine, a sole-support, means for locating a sole upon the support in a predetermined position, a sole-holder associated with the support, sole-transferring means acting between the holder and support, and automatic means at the holder arranged to adjust the soles both longitudinally and transversely to correspond to the position they are to occupy on the support.

221. In a machine of the class described, an article-container, a support upon which the articles are to occupy a predetermined position, means for feeding the articles from the container for delivery to the support, and means for moving the articles upon the feeding means to correspond to the predetermined position.

222. In a machine of the class described, an article-container, a support upon which the articles are to occupy a predetermined position, means for feeding the articles from the container for delivery to the support, and means acting during the feeding for moving the articles upon the feeding means to correspond to the predetermined position.

223. In a machine of the class described, a container from which articles may be delivered, and a plurality of bottom-portions therefor movable in the direction of delivery, said portions being connected to travel together but with a capability for independent movement during the operation of the machine.

224. In a machine of the class described, an article-container, a plurality of movable bottom-portions therefor, said portions being connected to travel together but with a capability for independent movement, and means arranged to resist the travel of a bottom-portion and thereby produce the independent movement.

225. In a machine of the class described, a container for a stack of articles, a slide mov-

able across the bottom of the container and upon which the lowermost article of the stack rests, an independently movable slide contacting with the edge of said article, and means for moving the last-mentioned slide. 70

226. In a machine of the class described, a container for a stack of articles, a slide movable across the bottom of the container and upon which the lowermost article of the stack rests, and an independently movable slide contacting with both an edge and the under side of said article. 75

227. In a machine of the class described, a container for a stack of articles, a slide movable across the bottom of the container and upon which the lowermost article of the stack rests, and independently movable slides contacting with opposite edges of said article. 80

228. In a machine of the class described, a container for a stack of articles, a primary slide movable across the bottom of the container and upon which the lowermost article of the stack rests, and a secondary feed-slide movable upon the primary slide during the operation of the machine and contacting with an edge of said article. 85

229. In a machine of the class described, a container for a stack of articles, a primary slide movable across the bottom of the container and upon which the lowermost article of the stack rests, a secondary feed-slide movable upon the primary slide and contacting with an edge of said article, and a slide arranged for contact with the opposite edge of the article. 95

230. In a machine of the class described, a container for a stack of articles, a primary slide movable across the bottom of the container and upon which the lowermost article of the stack rests, a secondary feed-slide movable upon the primary slide and contacting with an edge of said article, an adjacent slide arranged to contact with the opposite side of the article, and means carried by the secondary slide for moving the adjacent slide 110 against an article. 105

231. In a machine of the class described, a container for a stack of articles, a movable bottom-portion for supporting the stack, means for reciprocating said bottom-portion, slides for engagement with the articles, said slides being supported at opposite sides of the bottom-portion, and connections from the bottom-portion to the slides arranged to cause their movement with said bottom-portion 120 while permitting independent movement. 115

232. In a machine of the class described, a container for a stack of articles, a movable bottom-portion for supporting the stack, means for reciprocating said bottom-portion, slides for engagement with the articles, said slides being supported at opposite sides of the bottom-portion, one of them being mounted upon said bottom-portion, and connections from the bottom-portion to the slides 130

arranged to cause their movement with said bottom-portion while permitting independent movement.

233. In a machine of the class described, a container for a stack of articles, a movable bottom-portion for supporting the stack, means for reciprocating said bottom-portion, slides for engagement with the articles, said slides being supported at opposite sides of the bottom-portion, connections between the bottom-portion and one of the slides, and connections to the other slide into contact with which the first-mentioned connections are movable.

15 234. In a machine of the class described, a container for a stack of articles, a movable bottom-portion for supporting the stack, means for reciprocating said bottom-portion, slides for engagement with the articles, said 20 slides being supported at opposite sides of the bottom-portion, a spring resisting the movement of one of the slides, and connections from the bottom-portion to the slides arranged to cause their movement with said 25 bottom-portion while permitting independent movement.

235. In a machine of the class described, a container for a stack of articles, a movable bottom-portion for supporting the stack, said bottom-portion being provided with a 30 guide-way extending transversely to the direction of movement, means for reciprocating said bottom-portion, slides for engagement with the articles, said slides being supported 35 at opposite sides of the bottom-portion, a lever fulcrumed upon one slide and engaging the guide-way in the bottom-portion, and a lever fulcrumed upon the opposite slide, said last-mentioned lever being normally spaced 40 from the adjacent end of the lever of the companion slide and being engaged by it in the movement along the guide-way.

236. In a machine of the class described, a container for a stack of articles, a movable bottom-portion for supporting the stack, said bottom-portion being provided with a 45 guide-way extending transversely to the direction of movement, means for reciprocating said bottom-portion, slides for engagement with the articles, said slides being supported at opposite sides of the bottom-portion, a lever fulcrumed upon one slide and engaging the guide-way in the bottom-portion, a lever fulcrumed upon the opposite 50 slide, said last-mentioned lever being normally spaced from the adjacent end of the lever of the companion slide and being engaged by it in the movement along the guide-way, and springs acting upon the levers to 55 hold them yieldably in normal alignment.

237. In a sole-assembling machine, a container constructed to hold soles in a stack, a sole-support, means for locating a sole upon the support in a predetermined position, a feeding member arranged to move a sole

from the container for delivery to the support, and members contacting with the sole upon the feeding member to adjust it thereon to correspond to the predetermined position.

238. In a sole-assembling machine, a container constructed to hold soles in a stack, a sole-support, means for locating a sole upon the support in a predetermined position, a feeding member arranged to move a sole from the container for delivery to the support, 70 and members movable with the feeding member and contacting with the sole upon the feeding member to adjust it thereon to correspond to the predetermined position.

239. In a sole-assembling machine, a container constructed to hold soles in a stack, a sole-support, means for locating a sole upon the support in a predetermined position, a feeding member arranged to move a sole from the container for delivery to the support, 80 and members contacting with opposite sides of a sole upon the feeding member to adjust it thereon transversely to correspond to the predetermined position.

240. In a machine of the class described, 90 means for operating upon an article, an article-container, a table, means for feeding an article from the container to the table, means co-operating with the feeding means for adjusting the article during its feed, means for 95 transferring the article from the table to the operating means, and means for adjusting the position of the article upon the table in preparation for its transfer.

241. In a machine of the class described, an article-support, means for operating upon an article on the support, an article-container, a table adjacent to the container, means for feeding an article from the container to the table, means for adjusting the article during 100 its feed, means acting at a different angle than that during feed to adjust the article upon the table, and means for transferring the article from the table to the support, arranged to travel between the table and support.

242. In a machine of the class described, an article-support, means for operating upon an article on the support, an article-container, a table adjacent to the container, means for feeding an article from the container to the table, means co-operating with the feeding means for adjusting the article during its feed, means for transferring the article from the table to the support, and yieldable means 115 associated with the table and engaging the article thereon to hold it in the position to which it is adjusted during its feed.

243. In a machine of the class described, an article-support, means for operating upon an article on the support, an article-container, a table adjacent to the container, means for feeding an article from the container to the table, means co-operating with the feeding means for adjusting the article during its 125 feed.

feed, means associated with the table for adjusting the article thereon in another direction from the adjustment imparted during its feed, and means for transferring the article from the table to the support.

244. In a machine of the class described, an article-support, means for operating upon an article on the support, an article-container, a table adjacent to the container, means for feeding an article from the container to the table, means co-operating with the feeding means for adjusting the article during its feed, means for transferring the article from the table to the support, means associated with the table and engaging the article thereon to hold it yieldably in the position to which it is adjusted during its feed, and means for adjusting the article upon the table in another direction from the adjustment imparted during its feed.

245. In a sole-assembling machine, a sole-support, means for operating upon a supported sole, a container constructed to hold soles in a stack, a table adjacent to the container, a device movable to feed the lowest sole from the container to the table, a sole-transferring device movable between the table and support, and a member movable independently of the transferring device into contact with the sole after the completion of its feeding movement and arranged to adjust it before its transfer.

246. In a sole-assembling machine, a sole-support, means for operating upon a supported sole, a container constructed to hold soles in a stack, a table adjacent to the container, a device movable to feed the lowest sole from the container to the table, a sole-transferring device movable between the table and support, a member acting during the feed of the sole to adjust its position, and a member movable into contact with the sole upon the table to further adjust it before its transfer.

247. In a sole-assembling machine, a sole-support, means for operating upon a supported sole, a container constructed to hold soles in a stack, a table adjacent to the container, a device movable to feed the lowest sole from the container to the table, a sole-transferring device movable between the table and support, and means movable independently of the transferring device against a side and an end of the sole upon the table to adjust it longitudinally and transversely.

248. In a machine of the class described, an article-support, means for operating upon an article on the support, an article-container, a table adjacent to the container, means for feeding an article from the container to the table, means arranged to travel between the table and support for transferring the article from said table to said support, a gage associated with the table, and means for forcing

the article against the gage in preparation for its transfer.

249. In a machine of the class described, an article-support, means for operating upon an article on the support, an article-container, a table adjacent to the container, means for feeding an article from the container to the table, means for transferring the article from the table to the support, a gage associated with the table, means for grasping at opposite edges the article upon the table, and means for forcing the article thus grasped against the gage.

250. In a machine of the class described, an article-support, means for operating upon an article on the support, an article-container, a table adjacent to the container, means for feeding an article from the container to the table, means for transferring the article from the table to the support, a gage associated with the table, means for grasping the article upon the table, and means for forcing the article thus grasped against the gage, the grasping means being arranged to yield in the direction in which the article is forced.

251. In a machine of the class described, an article-support, means for operating upon an article on the support, an article-container, a table adjacent to the container, means for feeding an article from the container to the table, means for transferring the article from the table to the support, a gage associated with the table, means for grasping the article upon the table, means for forcing the article thus grasped against the gage, the grasping means being arranged to yield in the direction in which the article is forced, and an actuating member for the grasping and forcing means organized to cause first the release of the article by the grasping means and then by the forcing means.

252. In a sole-assembling machine, a sole-support, means for operating upon a supported sole, a container constructed to hold soles in a stack, a table adjacent to the support, a device movable to feed the lowest sole from the container to the table, a sole-transferring device movable between the table and support, a gage held against movement upon the table, and a member movable against the sole to carry it into contact with the gage.

253. In a sole-assembling machine, a container constructed to hold short soles having straight heel-ends, a table adjacent to the container, means for feeding the soles one by one from the container to the table, a gage associated with the table and having a surface extended laterally of said table, and a member movable against the toe-ends of the soles to carry substantially the entire length of the straight ends thereof into contact with the gage.

254. In a sole-assembling machine, a sole-support, means for operating upon a supported sole, a container constructed to hold soles

- in a stack, a table adjacent to the support, a device movable to feed the lowest sole from the container to the table, a sole-transferring device movable between the table and support, a gage associated with the table, members for oppositely grasping and temporarily yieldably holding the sole upon the table, and a member movable against the sole thus grasped to carry it into contact with the gage. 10
255. In a machine of the class described, an article-support, an article-receiving table, means for transferring an article from the table to the support, and means for locating the article upon the table for transfer and 15 consisting of opposite engaging members yieldable toward and from the article and along the surfaces engaged.
256. In a machine of the class described, an article-support, an article-receiving table, means for transferring an article from the table to the support, means for locating the article upon the table for transfer and 20 consisting of opposite engaging members yieldable toward and from the article and along the surfaces engaged, and a single spring arranged to permit the yield in both directions.
257. In a machine of the class described, an article-support, an article-receiving table, means for transferring an article from the table to the support, opposite article-engaging fingers associated with the table and pivoted upon axes substantially at right angles to each other, and means organized to impart to said fingers and their axes a movement of 25 translation.
258. In a machine of the class described, an article-support, an article-receiving table, means for transferring an article from the table to the support, opposite article-engaging fingers associated with the table and pivoted upon axes substantially at right angles to each other, a spring connecting the fingers, and means for bending the spring laterally. 30
259. In a machine of the class described, an article-receiving table, means for locating the article upon the table and consisting of opposite engaging members held normally toward each other and at one side of the article, and means for successively separating the members, moving them into the plane of the article, permitting them to close upon said article and moving them to one side thereof. 35
260. In a machine of the class described, an article-receiving table, a movable carrier situated adjacent to the table, levers fulcrumed upon the carrier, fingers mounted upon the levers for engagement with opposite sides of an article upon the table, and means for moving the carrier to cause the fingers to grasp and be drawn along the article. 40
261. In a machine of the class described, an article-receiving table, a movable carrier situated adjacent to the table, levers fulcrumed upon the carrier, fingers pivoted upon the levers for engagement with opposite sides of an article upon the table, and means for moving the carrier to cause the fingers to grasp and be drawn along the article. 45
- of an article upon the table, and means for moving the carrier to cause the fingers to grasp and be drawn along the article.
262. In a machine of the class described, an article-receiving table, a movable carrier situated below the table, levers fulcrumed upon the carrier, fingers pivoted upon the levers for engagement with opposite sides of an article upon the table, means for drawing the fingers toward each other and resisting their pivotal movement upon the levers, and means for moving the carrier to cause the fingers to grasp and be drawn along the article. 50
263. In a machine of the class described, an article-receiving table, a movable carrier situated below the table, levers fulcrumed upon the carrier, fingers mounted upon the levers for engagement with opposite sides of an article upon the table, an actuating member movable with the carrier, and gears connecting the actuating member and levers. 55
264. In a machine of the class described, an article-receiving table, a carrier movable toward and from the table, fingers mounted upon the carrier for engagement with opposite sides of an article upon the table, friction means for resisting the movement of the carrier, an actuating member movable through the carrier, and gears connecting the actuating member and fingers. 60
265. In a machine of the class described, an article-receiving table, a carrier movable toward and from the table, fingers pivoted upon the carrier for engagement with opposite sides of an article upon the table, an actuating member movable through the carrier, gears connecting the actuating member and fingers, and a helical spring connecting the fingers and bearing against the actuating member. 65
266. In a machine of the class described, a support upon which articles are to be operated on, means for holding an article, means for transferring the article from the holding means to the support, a plurality of means mounted independently of each other and acting to differently position the article preparatory to its transfer, and means arranged to control the action of one positioning means from the other. 70
267. In a machine of the class described, a support upon which articles are to be operated on, means for holding an article, means for transferring the article from the holding means to the support, a plurality of means acting to differently position the article preparatory to its transfer, connections arranged to move one of the positioning means from the other, and means acting as an incident to the movement to release the connections. 75
268. In a machine of the class described, a support upon which articles are to be operated on, means for holding an article, means for transferring the article from the holding means to the support, a normally fixed gage, 80

a plurality of means acting in co-operation with the gage to differently position the article preparatory to its transfer, and connections arranged to move one of the positioning means from the other, the positioning means thus moved having a portion permitting yield upon contact with the article.

269. In a machine of the class described, an article-support, an article-receiving table, means for transferring an article from the table to the support, members movable into contact with different portions of the article to position it upon the table, one of said members consisting of a lever, a reciprocatory actuating member for the members associated with the lever, and a pawl carried by the actuating member and contacting with the lever to effect its article-positioning movement.

270. In a machine of the class described, an article-support, an article-receiving table, means for transferring an article from the table to the support, members movable into contact with the different portions of the article to position it upon the table, one of said members consisting of a lever, a reciprocatory actuating member for the members associated with the lever, a pawl carried by the actuating member and contacting with the lever to effect its article-positioning movement, and a member into contact with which the pawl is moved to release the lever from the pawl.

271. In a machine of the class described, an article-support, an article-receiving table, means for transferring an article from the table to the support, members movable into contact with different portions of the article to position it upon the table, one of said members consisting of a lever including relatively yieldably sections, a reciprocatory actuating member for the members associated with the lever, and a pawl carried by the actuating member and contacting with the lever to effect its article-positioning movement.

272. In a sole-assembling machine, a sole-support, a table, a device movable to transfer a sole from the table to the support, opposite members movable against the sole upon the table to grasp it, a traveling actuating member for moving the grasping members, a member movable against the end of the grasped sole to position it upon the table, connections between the actuating member and positioning member effective during a portion of the travel of the former, and relatively fixed means acting upon the connections during the travel to effect their release.

273. In a machine of the class described, a container for relatively thin curved articles, said container having at one side a space through which the articles may pass, means arranged to hold one curved edge of each article elevated to bring the opposite edge into position to pass through the space, and means for feeding the articles through the space.

274. In a machine of the class described, a container for relatively thin curved articles, said container having at one side a space through which the articles may pass, means arranged to hold one curved edge of each article elevated to bring the opposite edge into position to pass through the space, and means for moving the elevating means to feed the articles through the space.

275. In a machine of the class described, a container for relatively thin curved articles, said container having at one side a space through which the articles may pass, means arranged to hold one edge of each article elevated to bring the opposite edge into position to pass through the space, and means for advancing the elevating means to feed the article partially through the space, for thereafter withdrawing the elevating means to permit the raised edge of the article to drop and for finally advancing the elevating means to further feed the article.

276. In a machine of the class described, a container for relatively thin curved articles, said container having at one side a space through which the articles may pass, means arranged to hold one curved edge of each article elevated to bring the opposite edge into position to pass through the space, and means for moving the elevating means to feed the articles through the space, the elevating means being provided with an extension effective while one article is being fed to support the associated articles in the container.

277. In a machine of the class described, an article-container having in its side a delivery space, and a feed-slide movable through the container-space, the inner edge of said slide being provided with a notch arranged to hold the edge of an article to be fed above the plane of the space and to engage said article to feed it through the space, the slide also having a surface below the notch arranged to engage and complete the feed of the article released from the notch.

278. In a machine of the class described, an article-container having in its side a delivery space, and a feed-slide movable through the container-space, the inner edge of said slide being provided with a notch arranged to hold the edge of an article to be fed above the plane of the space and to engage said article to feed it through the space, the slide also having an extension effective while one article is being fed to support the associated articles in the container.

279. In a machine of the class described, an article-container having in its side a delivery space, and a feed-slide movable through the container-space, the inner edge of said slide being provided with a notch arranged to hold the edge of an article to be fed above the plane of the space and to engage said article to feed it through the space, the slide also having an extension effective while one article is being fed to support the associated articles in the container.

title is being fed to support the associated articles in the container, the parts being arranged to permit the lowermost article during the return of the slide from the feeding movement to enter the notch.

280. In a machine of the class described, an article-container having in its side a delivery space, a bottom-portion movable from the container and passing below the delivery space, and a feed-slide carried by the bottom-portion and arranged to hold elevated above the delivery space the edge of a contained article opposite said space.

281. In a machine of the class described, an article-container having in its side a delivery space, a bottom-portion movable from the container and passing below the delivery space, a feed-slide carried by the bottom-portion and arranged to hold elevated above the delivery space the edge of a contained article opposite said space, and means for moving the slide upon the bottom-portion to position the article upon said bottom-portion.

282. In a sole-assembling machine, a container for molded soles, said container having at the lower portion of one side a space through which the soles are delivered, a member arranged to elevate one of the curved sides of the forepart of a sole and thus lower the opposite curved side into the horizontal plane of the delivery space, and means for feeding the thus positioned sole through the delivery space.

283. In a sole-assembling machine, a container for molded soles, said container having at the lower portion of one side a space through which the soles are delivered, a movable member arranged to elevate one of the curved sides of the forepart of a sole and thus lower the opposite curved side into the horizontal plane of the delivery space, and means for moving the elevating member to feed the thus positioned sole through the delivery space.

284. In a sole-assembling machine, a container for molded soles, said container having at the lower portion of one side a space through which the soles are delivered, a movable member arranged to elevate one of the curved sides of the forepart of a sole and thus lower the opposite curved side into the horizontal plane of the delivery space, and means for reciprocating the elevating member to feed the thus positioned sole partially through the delivery space, to release the sole to permit the elevated edge to drop and then to complete the feeding of the sole through the space.

285. In a machine of the class described, a transferring device, a container having a plurality of sections each arranged to hold a series of articles, means for moving the container after each operation of the transferring device to successively present terminal articles of the series in different sections to

the transferring device, and means for moving the series of articles through the sections to bring them into successive co-operation with the transferring device.

286. In a machine of the class described, a movable transferring device, a support, a rotatable container having a plurality of article-holding sections between which and the support the transferring device moves, means for rotating the container after each operation of the transferring device to successively present the articles in different sections to the transferring device, and means for imparting to the articles a movement along the axis of rotation to bring successive layers of articles in the plural sections into the desired plane for engagement by the transferring device.

287. In a machine of the class described, a transferring device, a container having a plurality of article-holding sections, and means for imparting to the articles in all the sections a helical movement to present them to the transferring device.

288. In a sole-assembling machine, a sole-support, a shank-piece-transferring device co-operating therewith, a container having a plurality of sections each arranged to hold a stack of shank-pieces, means for rotating the container to successively present the shank-pieces in different sections to the transferring device, and means for imparting to the shank-pieces upon each rotation of the container a movement along the sections toward the transferring device, such movement being substantially equal to the thickness of a shank-piece.

289. In a machine of the class described, a rotatable container having a plurality of article-holding sections, an article-supporting member in each section, and means for moving the members simultaneously through the sections to prepare the supported articles for delivery.

290. In a machine of the class described, a rotatable container having a plurality of article-holding sections, a movable member having arms lying in the container-sections, and means for moving the arms through the sections.

291. In a machine of the class described, a container having an axial space and a circular series of article-receiving spaces, a member supported in the axial space and having portions extending into the receiving spaces, and means for moving the member longitudinally of the axis.

292. In a machine of the class described, a rotatable container having an axial space and a circular series of article-receiving spaces, a member supported in the axial space and having portions extending into the receiving spaces, means for moving the member longitudinally of the axis, and means for rotating the container.

293. In a machine of the class described, a rotatable container having an axial space and a circular series of article-receiving spaces, a member supported in the axial space and having portions extending into the receiving spaces, and means made effective in the rotation of the container for moving the member longitudinally of the axis. 70
294. In a machine of the class described, 10 rotatable receiving means having a plurality of article-holders, article-supporting means movable through each holder, a threaded portion common to all the supporting means, a relatively fixed threaded portion engaging 15 that of the supporting means, and means for rotating the supporting means to cause its travel along the threaded portion. 75
295. In a machine of the class described, 20 rotatable receiving means having a plurality of article-holders, article-supporting means movable through each holder, a threaded portion common to all the supporting means, a relatively fixed threaded portion engaging 25 that of the supporting means, and means for rotating the receiving means, there being contact between the receiving means and supporting means to cause the rotation and consequent travel through the receiving 30 means of the supporting means. 80
296. In a machine of the class described, a container having a plurality of article-holding sections, an article-supporting member in each section, means for moving the members simultaneously to prepare the supported articles for delivery, means for moving the container for successive delivery from its sections, and means arranged for manual actuation to free the supporting members from their moving means and permit the return of the supporting members to the initial 40 position. 85
297. In a machine of the class described, 45 rotatable article-receiving means, article-supporting means movable through the article-receiving means and having a threaded portion, a relatively fixed threaded portion engaging that of the supporting means, means for rotating the supporting means to cause its travel along the threaded portion, and means arranged to release the engagement of the threaded portions. 90
298. In a machine of the class described, 50 rotatable article-receiving means, article-supporting means movable through the article-receiving means and having a threaded portion, a relatively fixed threaded portion engaging that of the supporting means, one of the threaded portions having separable sections to permit its disengagement from the other, and means for rotating the supporting means to cause its travel along the threaded portion. 100
299. In a machine of the class described, a 55 rotatable plate, vertical walls radiating from about the axis of the plate and furnishing intermediate article-receiving spaces, gearing for rotating the plate, a rotatable member having arms projecting into the receiving spaces and arranged to move longitudinally through the spaces and support articles 70 therein, a nut carried by the supporting member, and a relatively fixed screw for engagement with the nut. 75
300. In a machine of the class described, a 60 rotatable plate, vertical walls radiating from about the axis of the plate and furnishing intermediate article-receiving spaces, gearing for rotating the plate, a rotatable member having arms projecting into the receiving spaces and arranged to move longitudinally through the spaces and support articles 75 therein, a nut having separable sections carried by the supporting member, and a relatively fixed screw for engagement with the nut. 80
301. In a machine of the class described, 80 article-supporting means, means for rotating the supporting means, and means for causing longitudinal movement of the supporting means and including a screw, a casing 85 surrounding the screw, a sectional nut arranged in the casing for engagement with the screw, means tending to separate the nut-sections from engagement with the screw and means for maintaining normal engagement 90 of the nut-sections and screw. 95
302. In a machine of the class described, 90 article-supporting means, means for rotating the supporting means, and means for causing longitudinal movement of the supporting means and including a screw, a casing 100 surrounding the screw, a sectional nut arranged in the casing for engagement with the screw, a spring situated between the sections and exerting its force to separate them 105 and a spring effective to maintain normal engagement of the nut and screw. 110
303. In a machine of the class described, 105 article-supporting means, means for rotating the supporting means, and means for causing longitudinal movement of the supporting means and including a screw, a casing 115 surrounding the screw, a sectional nut arranged in the casing for engagement with the screw, the casing and nut having co-operating inclined surfaces and being arranged for relative longitudinal movement, a spring effective to maintain engagement between the inclined surfaces with the nut-sections and screw in engagement and springs situated between the sections and acting to disengage them from the screw upon relative longitudinal movement of the casing and nut. 120
304. In a machine of the class described, 120 an article-container having a rotatable plate and a plurality of vertical walls radiating about the axis with intermediate radial spaces, and removable article-holders carried in the spaces. 125
305. In a machine of the class described, 130

an article-container having a plurality of article-receiving spaces, a holder for each space, each holder having a longitudinal opening, and an elevating member for the articles having projections movable through the openings in the holders.

306. In a machine of the class described, an article-container having a rotatable plate and a plurality of vertical walls radiating about the axis with intermediate radial spaces, removable article-holders carried in the spaces and having at their lower extremities a less transverse dimension than the contained articles, and elevating members arranged to act upon the articles through the contracted ends.

307. In a machine of the class described, an article-container having a rotatable plate and a plurality of vertical walls radiating about the axis with intermediate radial spaces, removable article-holders carried in the spaces and having longitudinal openings at the sides toward the axis, and a member movable along the axis of the container and having arms projecting through the openings.

308. In a machine of the class described, an article-container having a rotatable plate and a plurality of vertical walls radiating about the axis with intermediate article-receiving spaces, electric heating units contained in the walls, collector-rings mounted to rotate with the container and joined to the units, and contact members for delivering current to the rings.

309. In a machine of the class described, a magazine arranged to contain a stack of articles, an article-support, a transferring device arranged to lift an article from the container and deposit it upon the support, and means arranged to vary in the travel of the transferring device the position in which said device deposits the transferred article.

310. In a machine of the class described, a work-support, a magazine arranged to contain a stack of articles, a device arranged to lift an article from the container and deposit it upon the support, and automatic means arranged to vary the position in which the transferring device applies the article to the support.

311. In a machine of the class described, a work-support, an article-container, a device movable to transfer an article from the container to the support, and means arranged to vary in a predetermined manner the position transversely to its direction of travel at which the transferring device applies the article to the support.

312. In a machine of the class described, a work-support, an article-container, a device for transferring an article from the container to the support, means for determining the direction in which the transferring device

moves, and means arranged to vary the effect of the direction-determining means.

313. In a machine of the class described, an article-container and an article-support, a transferring device operating under the power of the machine between the container and support, a guide for the transferring device, and means arranged to vary the position of the guide.

314. In a machine of the class described, an article-container and an article-support, a transferring device operating between the container and support, an angularly movable guide for the transferring device, and means arranged to fix the guide in different angular positions to vary the effect of the transferring device.

315. In a machine of the class described, a work-support, an article-container, an arm pivoted between the support and container and being movable about its pivotal axis and longitudinally thereof, an article-transferring device mounted upon the arm and acting between the container and support, means for moving the arm about its pivot, and means for moving said arm along its pivot.

316. In a machine of the class described, a work-support, an article-container, an arm pivoted between the support and container and being movable about its pivotal axis and longitudinally thereof, an article-transferring device mounted upon the arm and acting between the container and support, means for moving the arm about its pivot, a track, and a member movable with the arm and engaging the track.

317. In a machine of the class described, a work-support, an article-container, an arm pivoted between the support and container and being movable about its pivotal axis and longitudinally thereof, an article-transferring device mounted upon the arm and acting between the container and support, means for moving the arm about its pivot, a track arranged for angular movement, means arranged to fix the track in different angular positions, and a member movable with the arm and engaging the track.

318. In a composite-sole-assembling machine, a sole-support, a container for shank-pieces, and a device arranged to engage and lift a shank-piece from the container and apply it to a sole upon the support.

319. In a composite-sole-assembling machine, a sole-support, a container for shank-pieces, a device for heating the shank-pieces, and a device arranged to engage and lift a shank-piece from the container and apply it to a sole upon the support.

320. In a composite-sole-assembling machine, a sole-support, a container for sole-elements, a transferring device movable between the container and support, and means arranged to vary the relation transversely of

the support in which the transferring device delivers the sole-element to correspond to a right or a left sole.

321. In a composite-sole-assembling machine, a sole-support, a container for shank-pieces, a device for transferring a shank-piece from the container to the sole upon the support, and means arranged to vary the movement of the transferring device to correspond to a right or a left sole.

322. In a machine of the class described, a work-support, an article-holder, means movable between the holder and support for transferring an article from the holder to a point above but without contact with the support, and means arranged to temporarily hold the article at the position to which it is thus transferred.

323. In a machine of the class described, a work-support, an article-container, means movable beneath the container to a point over the support for transferring an article from the container in proximity to but without contact with the support, and a member arranged to temporarily hold the article at the position to which it is thus transferred and to thereafter carry it into contact with the support.

324. In a machine of the class described, a movable work-support, an article-container, means movable independently of the support to feed an article from the container to a position in proximity to the support, means for holding the article at the point to which it is fed, and means for moving the holding means to carry the article into cooperation with the support.

325. In a machine of the class described, a work-support, an article-container, means for transferring an article from the container in proximity to but without contact with the support, and a member having projections arranged to enter and temporarily hold the article at the position to which it is thus transferred.

326. In a machine of the class described, a work-support, an article-container, means for transferring an article from the container in proximity to the support, and a gravity-actuated member having projections arranged to enter and temporarily hold the article at the position to which it is thus transferred.

327. In a machine of the class described, a work-support, an article-container, means for transferring an article from the container in proximity to the support, a spring-actuated member having projections arranged to enter and temporarily hold the article at the position to which it is thus transferred, and power means for moving the member to deliver the article to the support.

328. In a machine of the class described, a work-support, an article-container, means for transferring an article from the container in proximity to the support, and means movable

into engagement with the transferred article and controlled by the transferring means and arranged to temporarily hold the article at the position to which it is thus transferred.

329. In a machine of the class described, an article-container, a support to which an article from the container is to be applied in a definite relation, means for transferring an article from the container into correct alignment with the support, and means movable into engagement with the article while thus aligned for holding it in such alignment during the retreat of the transferring means.

330. In a machine of the class described, a work-support, an article-container, means arranged to support an article at the container and movable to feed said article from the container into alignment with the support, means for engaging the article and temporarily maintaining it in such alignment, and means for moving the engaged article into co-operation with the support.

331. In a machine of the class described, an article-container, a support to which an article from the container is to be applied in a definite relation, means for transferring an article from the container into correct alignment above the support, means movable into engagement with the article after such transfer, said engaging means being actuated to effect this engagement, and means other than that causing the engagement arranged to lower the article in the desired relation to the support.

332. In a machine of the class described, a work-support, an article-container, an article-carrying slide movable from the container over the support, means for reciprocating the slide, and means for engaging an article brought by the slide in its travel from the container and to support it during reverse movement of the slide.

333. In a machine of the class described, a work-support, an article-container, an article-carrying slide movable from the container over the support, means for reciprocating the slide, means for engaging an article brought by the slide in its travel from the container and to retain it during reverse movement of the slide, and means for moving the engaging means to deliver the article to the support.

334. In a machine of the class described, a work-support, an article-container, a slide movable through the lower portion of the container and having an article-carrying depression, said depression being open at the end toward the support, means for reciprocating the slide between the container and support, and a member arranged to engage an article in the slide-depression upon movement from the container to the support and to hold it for withdrawal through the open end upon reverse movement of the slide.

335. In a machine of the class described, a work-support, an article-container, an arti-

cle-carrying slide movable from the container over the support, means for reciprocating the slide, and a member co-operating with the support and having projections arranged to be forced into an article brought by the slide in its travel from the container and to support said article upon the retreat of the slide.

336. In a machine of the class described, a work-support, an article-container, means for reciprocating a slide movable from the container over the support, a member co-operating with the support and having projections arranged to be forced into an article brought by the slide in its travel from the container, and means for moving the member to deliver the article to the support.

337. In a machine of the class described, a work-support, an article-container, an article-carrying slide movable from the container over the support, means for reciprocating the slide, a spring-actuated member co-operating with the support and having projections arranged to be forced into an article brought by the slide in its travel from the container, means for latching the member against actuation, and means controlled in the movement of the slide for releasing the latch.

338. In a machine of the class described, an article-container, a work-support, ways extending from the bottom of the container at opposite sides of the support, an article-transferring slide movable from the container along the ways over the support, and an article-delivering member movable into engagement with an article upon the slide and thereafter into co-operation with the support.

339. In a composite-sole-assembling machine, a support arranged for contact with a sole, means for placing a sole with its tread-surface against the support, mechanism for applying a retaining means to the upper surface of the supported sole, a filler-piece-container, and means for removing a filler-piece from the container and applying it to the inner face of the sole and to the retaining means, the removing and applying means being arranged to position the filler-piece over an area spaced inwardly from the periphery of the sole.

340. In a machine of the class described, a work-support, an article-container situated at one side of the support, and means for transferring an article from the container to a point above the support and then upon said support, said transferring means being arranged to apply pressure to mold the article.

341. In a machine of the class described, a work-support, an article-container, means for transferring an article from the container in proximity to but without contact with the support, means arranged to temporarily hold the article at the position to which it is thus transferred, said holding means being pro-

vided with a pressure-surface, and means for moving said holding means to apply pressure by its surface to the article.

342. In a machine of the class described, a work-support, an article-container, means movable to feed an article from the container to a position in proximity to the support, means for holding the article fed, said holding means being arranged to move into engagement with the article, and independent means for moving the holding means to carry the article into co-operation with the support and to apply pressure to it.

343. In a machine of the class described, a work-support, an article-container, reciprocating means movable to feed an article from the container to a position in proximity to the support, means for engaging the article upon the feeding means and holding it during the withdrawal of the feeding means, and means for moving the holding means to press the article into co-operation with the support.

344. In a machine of the class described, a work-support, an article-container, means movable to feed an article from the container to a position in proximity to the support, spring-actuated means arranged to engage and hold the article fed, and fluid-pressure means for moving the holding means toward the support.

345. In a machine of the class described, a work-support, an article-container, a carrier arranged to move in proximity to the container and toward and from the support, a pressure member arranged for co-operation with the support and movable upon the carrier, means movable to deliver articles into the path of the pressure member, and means for latching the pressure member upon the carrier out of the path of the delivering means, said pressure member being arranged for release to engage the delivered article.

346. In a machine of the class described, a work-support, an article-container, a carrier arranged to move in proximity to the container and toward and from the support, a pressure member arranged for co-operation with the support and movable upon the carrier, means movable to deliver articles into the path of the pressure member, means for latching the pressure member upon the carrier out of the path of the delivering means, said pressure member being arranged for release from the latching means to engage the delivered article, and means for moving the pressure member into co-operation with the support.

347. In a machine of the class described, a work-support, an article-container, a carrier arranged to move in proximity to the container and toward and from the support, a pressure member arranged for co-operation with the support and movable upon the carrier, means movable to deliver articles into the path of the pressure member, means for latch-

ing the pressure member upon the carrier out of the path of the delivering means, said pressure member being arranged for release to engage the delivered article, a spring for actuating the released pressure member, a piston connected to the carrier member, and a power cylinder in which the piston operates.

348. In a machine of the class described, a work-support, an article-container, a carrier arranged to move in proximity to the container and toward and from the support, a pressure member arranged for co-operation with the support and pivoted upon the carrier, a latch for the carrier to retain the pressure member in a normal position, and means movable to deliver articles adjacent to the latched pressure member, said means co-operating in its movement with the latch to release it.

349. In a machine of the class described, a work-support, an article-container, a carrier arranged to move in proximity to the container and toward and from the support, a pressure member arranged for co-operation with the support and movable upon the carrier, said pressure member being provided with article-engaging projections, means movable to deliver articles into the path of the pressure member, and means for latching the pressure member upon the carrier out of the path of the delivering means, said pressure member being arranged for release to permit the projections to enter the delivered article.

350. In a machine of the class described, a work-support, an article-container, a carrier arranged to move in proximity to the container and toward and from the support, a pressure member arranged for co-operation with the support and movable upon the carrier, said pressure member being provided with article-engaging projections, means movable to deliver articles into the path of the pressure member, means for latching the pressure member upon the carrier out of the path of the delivering means, said pressure member being arranged for release to permit the projections to enter the delivered article, and means for moving the pressure member into co-operation with the support after the engagement of the article by the projections.

351. In a machine of the class described, a work-support, an article-container, an article-carrying slide movable from the container over the support, means for reciprocating the slide, and means for engaging an article brought by the slide in its travel from the container and to retain it during reverse movement of the slide, and means for pressing the article between the engaging means and support.

352. In a machine of the class described, an article-container, a work-support, ways extending from the bottom of the container at

opposite sides of the support, an article-transferring slide movable from the container along the ways over the support, and a member having projections movable into engagement with an article upon the slide and thereafter between the ways to press the engaged article toward the support.

353. In a composite-sole-assembling machine, a support having a receiving surface generally corresponding in contour to a molded sole, a filler-piece-container, means for removing a filler-piece from the container and presenting it for application to a sole upon the support, and a pressure member having a surface acting upon the presented filler-piece, said surface co-operating with and conforming to the supporting surface.

354. In a composite-sole-assembling machine, a support having a receiving surface generally corresponding in contour to a molded sole, a filler-piece-container, means for removing a filler-piece from the container and presenting it for application to a sole upon the support, and a pressure member having a surface acting upon the presented filler-piece, said surface of the pressure member being provided with means for engaging and retaining the presented filler-piece.

355. In a composite-sole-assembling machine, a support having a receiving surface generally corresponding in contour to a molded sole, a filler-piece-container, means for removing a filler-piece from the container and presenting it for application to a sole upon the support, a member having a surface situated opposite and conforming to the supporting surface and provided with projections, said member being arranged for actuation to cause the projections to enter the presented sole, and means for forcing the member toward the support to press the filler-piece against the sole thereon.

356. In a machine of the class described, a portable container having walls arranged to hold contained articles against displacement by frictional engagement with them, means for retaining the container in position to adapt it for the delivery of its contents, and means operating upon the container when thus retained to free the contained articles from the holding engagement of the walls.

357. In a machine of the class described, a portable tubular container having a longitudinal division and with the walls upon each side of the division yieldable from each other and arranged to engage contained articles to hold them against displacement, means for retaining the container in position to adapt it for the delivery of its contents, and means arranged to enter the space between the walls to separate them to free the contained articles for delivery.

358. In a machine of the class described, a portable tubular container having a longitudinal division and with the walls upon

- each side of the division yieldable from each other and arranged to engage contained articles to hold them against displacement, means for retaining the container in position to 5 adapt it for the delivery of its contents, and a member mounted upon the retaining means and movable into the space between the walls to separate them and free the contained articles for delivery.
- 10 359. In a machine of the class described, a portable tubular container having a longitudinal division and with the walls upon each side of the division yieldable from each other and arranged to engage contained articles to hold them against displacement, posts between which the container is supported, the space between the walls being adjacent to one of the posts, and a wedge movable upon the post into the space.
- 15 360. In a machine of the class described, a portable tubular container having a longitudinal division and with the walls upon each side of the division yieldable from each other and arranged to engage contained articles to hold them against displacement, means for retaining the container in position to adapt it for the delivery of its contents, wedges mounted upon the support at opposite sides of the longitudinal center of the container, and means arranged to force the wedges simultaneously into the space between the container-walls.
- 20 361. In a machine of the class described, a portable container having walls arranged to hold contained articles against displacement by frictional engagement with them, movable means for retaining the container in position to adapt it for the delivery of its contents, and means carried by the retaining means and arranged to operate upon the container in its movement to free the contained articles from the engagement of the walls.
- 25 362. In a machine of the class described, a portable tubular container having a longitudinal division and with the walls upon each side of the division yieldable from each other and arranged to engage contained articles to hold them against displacement, posts between which the container is supported, one 30 of said posts being pivoted, and a wedge carried upon the pivoted post and arranged in the movement thereof to enter the space between the container-walls.
- 35 363. In a composite-sole-assembling machine, a filler-piece magazine comprising a sheet-metal tube having separable walls substantially conforming in transverse section to the external contour of the filler-pieces and engaging the edges of said filler-pieces 40 to hold them against longitudinal displacement, means for retaining the magazine in position to adapt it for the delivery of its contents, and means for separating the magazine-walls to free the filler-pieces for such delivery.
364. In a machine of the class described, mechanism for operating upon the work, power mechanism, means for governing the application of power to the operating mechanism, a heating device associated with the operating mechanism, a second heating device co-operating with and bearing in the heat emitted some predetermined relation to the device first mentioned, and means controlled by the second heating device for operating the governing means.
- 45 365. In a machine of the class described, mechanism for operating upon the work, power mechanism, variable connections between the operating mechanism and power mechanism, a device associated with the operating mechanism and acting upon a work-portion, a second device similar to and co-operating with the device first mentioned and bearing in its effect some predetermined relation thereto, and means controlled by the second device for operating the power connections.
- 50 366. In a machine of the class described, mechanism for operating upon the work, power mechanism, means for governing the application of power to the operating mechanism, an electric device acting upon the operating mechanism, a second similar electric device in circuit with the first and bearing a predetermined relation thereto in the effect produced, and means arranged to control the governing means under the influence of said second electric device.
- 55 367. In a machine of the class described, mechanism for operating upon the work, power mechanism, movable connections between the operating mechanism and power mechanism, an electric heating unit associated with the operating mechanism, and a second electric heating unit in circuit with the first and arranged to control the power connections.
- 60 368. In a machine of the class described, mechanism for operating upon the work, power mechanism, movable connections between the operating mechanism and power mechanism, an electric heating unit associated with the operating mechanism, a second electric heating unit in circuit with the first and designed to emit heat bearing a predetermined relation to that produced by the unit at the operating mechanism, and means arranged to control the power connections under the influence of said second heating unit.
- 65 369. In a machine of the class described, mechanism for operating upon the work, power mechanism, a clutch for connecting the power mechanism and operating mechanism, a heating device associated with the machine, and power means controlled by the heating device for actuating the clutch.
- 70 370. In a machine of the class described, mechanism for operating upon the work, power mechanism, a clutch for connecting the

power mechanism and operating mechanism, fluid-pressure mechanism for actuating the clutch, a thermostatic device arranged to control the fluid-pressure mechanism, and means for applying heat to the operating mechanism and for actuating the thermostatic device.

371. In a machine of the class described, mechanism for operating upon the work, 10 power mechanism, a clutch for connecting the power mechanism and operating mechanism, fluid-pressure mechanism for actuating the clutch, an electric heating unit associated with the operating mechanism, a second electric 15 heating unit in circuit with that of the operating mechanism, a thermostatic device under the influence of said second unit, and fluid-pressure mechanism arranged to actuate the clutch under the control of the thermostatic 20 device.

372. In a machine of the class described, mechanism for operating upon the work, a source of power, a fluid-pressure system, mechanism arranged for operation by the 25 fluid-pressure system, mechanism arranged for operation by the fluid pressure to apply power from the source to the operating mechanism, and means depending upon a condition at the operating mechanism for controlling the fluid pressure at the power-applying mechanism.

373. In a machine of the class described, mechanism for operating upon the work, a source of power, a fluid-pressure system including a leak-opening, mechanism arranged 35 for operation by the fluid pressure to apply power to the operating mechanism, and means depending upon a condition at the operating mechanism for controlling the leak-opening.

40 374. In a machine of the class described, mechanism for operating upon the work, a source of power, a fluid-pressure system including a leak-opening, mechanism arranged for operation by the fluid pressure to apply 45 power to the operating mechanism, a heating system acting upon the operating mechanism, and a thermostatic device arranged to control the leak-opening and being under the influence of the heating system.

50 375. In a machine of the class described, mechanism for operating upon the work, a source of power, a fluid-pressure system including a leak-opening, mechanism arranged for operation by the fluid pressure to apply power to the operating mechanism, an electric heating unit associated with the operating mechanism, a thermostat carrying a valve 55 cooperating with the leak-opening, and an electric heating unit in circuit with the unit at the operating mechanism for actuating the thermostat.

60 376. In a machine of the class described, mechanism for operating upon the work, a source of power, variable connections for de-

70 livering power from the source to the operating mechanism, a source of fluid pressure, means for applying fluid pressure to the power connections to actuate them, and means organized to prevent such application of fluid pressure save when it is of predetermined magnitude.

377. In a machine of the class described, mechanism for operating upon the work, a source of power, variable connections for 75 delivering power from the source to the operating mechanism, a continuously operating pump, means including a fluid-conduit for applying power generated by the pump to the power connections to actuate them, and means 80 controlled by the pressure in the conduit to govern the flow therethrough.

378. In a machine of the class described, mechanism for operating upon the work, a source of pressure, variable connections for 85 delivering power from the source to the operating mechanism, a continuously operating pump, means including a fluid-conduit for applying power generated by the pump to the power connections to actuate them, and 90 a valve in the conduit arranged to prevent such application of fluid pressure until it reaches a predetermined amount.

379. In a machine of the class described, mechanism for operating upon the work, a source of pressure, variable connections for 95 delivering power from the source to the operating mechanism, a continuously operating pump, means including a fluid-conduit for applying power generated by the pump to 100 the power connections to actuate them, a valve in the conduit arranged to prevent such application of fluid pressure until it reaches a predetermined amount, and an automatic valve arranged to relieve the pressure in the 105 conduit at a predetermined maximum.

380. In an assembling machine, a support, movable means for assembling articles upon the support, power mechanism from which the assembling means is moved, means for 110 governing the application of power to the assembling means, a heating device associated with the assembling means, and means controlled by the heating device for operating the governing means.

381. In an assembling machine, a support, movable means for assembling articles upon the support and including an adhesive-applying device, power mechanism from which the assembling means is moved, means for governing the application of power to the assembling means, a heating device associated with the adhesive-applying device, and means acting in accordance with the degree of heat applied to the adhesive-applying device for operating the governing means.

382. In an assembling machine, a support, movable means for assembling articles upon the support, a container for articles to be assembled, power mechanism from which the 130

assembling means is moved, means for governing the application of power to the assembling means, heating means associated with the container, and means acting in accordance with the degree of heat applied to the container for operating the governing means.

383. In a machine for operating upon a sole having a straight end, the combination with a support for the sole, means constructed and arranged to engage the sole-end at separated points, means for engaging the sole at another point, and means for moving said engaging means relatively to position the sole, said sole being capable of lateral movement upon the support under the influence of the engaging means.

384. In a machine for operating upon a sole having a straight end, a member provided with a surface upon which such sole is supported, a member constructed and arranged to engage the straight end of the sole at separated points, a member for engaging a point upon the sole at the opposite end, and means for moving the members relatively to cause the engagement with the sole at such points to position it angularly upon the supporting surface.

385. A machine for assembling parts of shoes, having, in combination, a support, a plurality of holders respectively for soles and for shoe-filters, and automatic mechanism for moving said support to present it in operative relation successively to said holders and for removing a part from each of said holders and depositing said parts successively upon said support.

386. A machine for assembling parts of shoes, having, in combination, a support for a part of a shoe, a rotary carrier for said support movable about a vertical axis, separate mechanisms for delivering a plurality of shoe-parts of different kinds successively to said support, and automatic mechanism for rotating said carrier intermittently and in synchronism with the delivering mechanisms for the deposit of a plurality of parts successively in predetermined relation to each other upon said support.

387. A machine for assembling parts of shoes, having, in combination, a plurality of supports for shoe-parts each presenting a supporting surface corresponding substantially to the vertical contour of a shoe-bottom, a horizontal turret carrying the supports, a holder for a stack of shoe-bottom-parts, and automatic mechanism for rotating said turret intermittently to present said supports successively in operative relation to said holder and for transferring parts from the holder and depositing them one at a time in predetermined position on the respective shoe-parts carried by said supports.

388. A machine for assembling parts of shoes, having, in combination, a work-sup-

port, holders respectively for stacks of soles and sheet shoe-filters, and intermittently acting power mechanism for relatively moving the support and the holders successively into operative relation and for transferring soles and filters from the respective holders into predetermined relative position on said support.

389. A machine for assembling parts of shoes, having, in combination, a support for a shoe-part, carriers for shoe-parts, adhesive-supplying means, and automatic mechanisms for causing the carriers to deliver differently formed shoe-parts to the support, for actuating said means to deliver adhesive upon a part delivered to said support by a carrier and for causing a carrier thereafter to deliver another shoe-part on said first part after the application of adhesive.

390. A machine for assembling parts of shoes, having, in combination, a support, a plurality of holders for shoe-parts, and automatic mechanisms for moving said support to present it in operative relation successively to said holders, for removing a part from each of said holders and depositing said parts successively upon said support, for applying adhesive to the first part after it has been thus deposited and before the last shoe-part to be assembled therewith has been deposited and for thereafter holding said parts under pressure a considerable period of time.

391. A machine for assembling parts of shoes, having, in combination, a support, a sole-holder, a shoe-filler-holder, and automatic mechanisms for transferring soles and filters from said respective holders and depositing them successively upon said support.

392. A machine for assembling parts of shoes, having, in combination, a support, mechanism for causing the travel of the support to different positions, a shoe-filler-holder at one position, mechanism at said position for transferring a filler from the holder to said support, a sole-holder at a different position, and mechanism at this position for transferring a sole from its holder to said support.

393. A machine for assembling parts of shoes, having, in combination, a rotary turret, a plurality of supports mounted upon the turret, mechanism for intermittently rotating the turret to cause each support to occupy successive positions, mechanism at one position for delivering a sole to each support, and mechanism at another position for delivering another shaped shoe-bottom-part to the support, the several mechanisms being actuated automatically and in synchronism.

394. A machine for assembling parts of shoes, having, in combination, a plurality of supports, mechanism for moving the supports to successive operating positions, means for delivering shoe-parts to the supports at such successive positions, and means for applying to one of the parts thus de-

livered an adhesive for maintaining the association of that part and another part to be delivered thereto.

395. In a composite-sole-assembling machine, a support, a sole-container, means for transferring a sole from the container to the support, a container for auxiliary sole-portions, means for transferring an auxiliary portion from the container to the sole upon the support, and means for shifting the auxiliary portion during its transfer and independently of the transferring movement.

396. In a composite-sole-assembling machine, a support, a sole-container, means for transferring a sole from the container to the support, a cement-receptacle, mechanism for delivering cement from the receptacle to the sole upon the support, means arranged to vary the application of cement to the sole, a shank-piece-container, means for transferring a shank-piece from its container to the

cemented area of the sole, and means for shifting the shank-piece to correspond to the manner in which the cement is applied to the sole.

25

397. In a machine for assembling composite molded soles, a sole-container having a bottom wall upon which the forepart of a sole may rest, a support within the container for the heel-portion of the sole, and a feeding device movable into engagement with the sole resting upon the bottom wall and support.

30

398. In a machine of the class described, an article-container having a plurality of walls radiating about an axis with vertical spaces intermediate the walls, article-holders carried by the spaces, and a heating device contained in the walls.

35

In testimony whereof I have signed my name to this specification.

FREDERICK M. FURBER
